[57] **ABSTRACT**

Tufting machines for making U-tufts and/or loop-tufts on a backing. The tufts may be made of the same or different heights and from strands of tufting material having the same or different color or other characteristics. Some machines form U-tufts and/or loop-tufts from discrete bits of tufting material whereas others form loop-tufts and/or U-tufts from a continuous strand. For tufts of the same or different color and of the same or different length, the pile pattern may be changed by controlling the number of rows of tufts per unit length of the backing; the number of tufts per row (gage), and the relative positions of corresponding tufts of different rows. All of the machines utilize at least one, and usually more, of the following means in cooperative combinations; tufting needle means including split-eye needles of novel construction and mode of control for opening and/or closure of the needle eyes; forked-end tufting blades which slit the backing and force the strands through the backing to form loop-tufts; novel adjustable bit-stop means at the tufting stations; strand-clamping means of novel construction at the tufting stations and/or in advance of strand-severing means; strand-severing means of novel rotary cutter and anvil construction used in various combinations of single cutter/single anvil, multiple-cutter/single anvil, and multiple-cutter/multiple anvil to supply a tufting station with tufting material of selected length and/or of selected color or other characteristics; novel cutter/anvil arrangements for making cut and/or uncut loop-tufts from continuous strands and in which blades of the cutter slit the backing, force the strands through the backing into the anvil recesses, and, for cut loop-tufts, cooperate with knife means in anvil recesses; for slitting the backing, the tufting blades may be fixed to a rotary member, or may be retractably mounted on a rotary cutter member, fixedly attached to a reciprocating member, slidably mounted in a stationary member and operated by a cam or other means, or slidably mounted in a reciprocating member; the tufting anvil may be a rotary structure or a belt structure, segmented or continuous, having upstanding recess-forming elements attached to the belt or integral therewith; means including mechanism for effecting adjustable step-by-step lengthwise feed of the backing; means including novel mechanism for effecting relative motion between the backing and a row of tufting-needle means in direction laterally of the lengthwise feed of the backing.

TUFTING MACHINES FOR MANUFACTURE OF TUFTED FABRICS, TUFTED CARPETS, RUGS, DRAPES, HEAVY FABRICS, AND THE LIKE

CROSS-REFERENCE TO RELATED APPLICATION

In some of its respects, this application is related to copending Spanel and Brennan application, Ser. No. 697,268, filed Dec. 18, 1967, now U.S. Pat. No. 3,554,147, continuation-in-part of their now abandoned application, Ser. No. 680,813, filed Nov. 6, 1967.

BACKGROUND OF THE INVENTION

In general and in some respects, the present invention is in the nature of modifications of or improvements upon tufting machines such as shown in the aforesaid Spanel and Brennan application and in Spanel and Barton U.S. Pat. No. 3,387,577.

BRIEF DESCRIPTION OF THE DRAWINGS

FIG. 1, schematically and partly in section, illustrates various components of a basic mechanism for cutting, feeding and applying bits to a backing to form U-tufts;

FIG. 1A is a detail view showing in side elevation the bit-threading position of a tufting needle of split-eye usable in FIG. 1;

FIGS. 1B and 1C are detail views showing in front and side elevation respectively, the threaded tufting needle of FIG. 1A;

FIG. 1D is a detail view showing a modification of the bit-stop arrangement of FIG. 1;

FIG. 1AA is a detail view showing, in side elevation, a modification of the tufting needle shown in FIG. 1A;

FIG. 2 is a perspective view of a removable knife for the cutter bar shown in FIG. 1;

FIG. 2A is a fragmentary detail view showing the knife of FIG. 2 in a knife and anvil assembly;

FIGS. 3, 3A, 4 and 4A are explanatory Figures referred to in discussion of some of the tufting patterns obtainable with the cutter bar arrangement shown in FIG. 1;

FIG. 5 is a fragmentary detail view, partly in section, of another bit-stop arrangement usable in the basic mechanism of FIG. 1;

FIGS. 6 to 6C are explanatory Figures referred to in discussion of different knife arrangements of the cutter bar;

FIG. 7 schematically illustrates an adjustable backing-feed arrangement usable in the basic mechanism of FIG. 1;

FIG. 7A is an explanatory FIGURE referred to in discussion of FIG. 7;

FIG. 8 is a fragmentary view, partly in section, of an arrangement for varying the lateral position of the applied bite;

FIG. 9, schematically and partly in section, shows a modification of the basic mechanism of FIG. 1 which permits selection of the length and/or color of bits supplied to a tufting station;

FIG. 9A shows, in perspective, an arrangement for automatically changing the position of the bit-stop of FIG. 9;

FIGS. 10 and 10A, schematically and partly in section, illustrate other modifications of FIG. 1 providing for color selection and using a single cutter bar/anvil arrangement;

FIG. 11 is a detail view of one of the strand-clamping means shown in FIG. 10;

FIG. 12 shows a modification of the strand-clamping means of FIG. 11;

FIG. 13 schematically illustrates a fluid system for retaining a desired cutting pressure for a rotary cutter bar and anvil combination;

FIG. 14 schematically illustrates a multi-strand selector having a plurality of cutter bars and a common anvil for selection of the length and/or color of bits supplied to a tufting station;

FIGS. 15 and 15A are detail views, in front and side elevation respectively, showing, in its threading position, a single needle having a tip-split eye and usable in FIG. 1 and other FIGURES;

FIG. 15B is a fragmentary detail view, in front elevation, of one form of the split-tip needle shown in FIGS. 15, 15A;

FIG. 15C is a plan view, in section, taken on line 15C—15C of FIG. 15B;

FIG. 15D is a fragmentary detail view, in front elevation, of another form of the split-tip needle shown in FIGS. 15, 15A;

FIG. 15E is a plan view, in section, taken on line 15E—15E of FIG. 15D;

FIGS. 16 and 16A are detail views, in front and side elevation respectively, showing the needle of FIGS. 15, 15A in its retracted position to form a pile loop;

FIG. 17 schematically shows an arrangement for bonding the underside bit-ends of loop pile shown in FIGS. 16, 16A and other FIGURES;

FIG. 18 is a detail view, showing in front elevation and in threading position, a dual needle of split-tip type shown in FIG. 15A and in subsequent Figures;

FIGS. 19 and 19A are detail views, in front elevation, showing the dual needle means of FIG. 18 in its retracted position to form two loop-tufts (FIG. 19), or a U-tuft (FIG. 19A);

FIG. 19B is a front elevational view showing, in its threading position, a tufting needle means of side-split eye type suited to form U- or loop-tufts when dual (FIGS. 19, 19A) and loop-tufts when single (FIG. 16);

FIG. 19C shows the needle means of FIG. 19B in retracted position with the loop-tuft freed from the needle;

FIG. 20 is a perspective view of a dual needle of a closed or unsplit-eye type;

FIGS. 21, 21A and 21B are perspective views showing different cutter-bar arrangements for supplying bits to dual closed-eye needles at different tufting stations;

FIG. 22 is a perspective view showing a series array of closed-eye and split-eye needles for making hybrid tufting at a tufting station;

FIG. 23 is a perspective view showing a parallel array of closed-eye and split-eye needles for making loop-tufts and U-tufts at different tufting stations;

FIG. 23A shows, in retracted position and in side elevation, a dual needle of split-eye type for making U- and loop-tufts from different length bits successively supplied to a tufting station;

FIGS. 24 and 24A show, in perspective, split-tip needle means suited for making loop pile or U-pile, each needle eye being opened and closed by linear motion (FIG. 24) or arcuate motion (FIG. 24A);

FIG. 24AA shows a multi-station array with common linear eye-control means for needles of split-tip type shown in FIG. 24;

FIGS. 24B, 24C and 24D are explanatory Figures referred to in discussion of a modification of FIG. 24A using needle means of side-split eye type similar to FIG. 19B;

FIGS. 24E, 24F and 24G are explanatory Figures corresponding with FIGS. 24B—24D but with arcuate movement of the other needle-shank member;

FIGS. 24H, 24I and 24J are explanatory Figures corresponding with FIGS. 24B—24D but with arcuate movement of both needle-shank members;

FIGS. 25, 25A, 25B are front elevational views of another form of split-tip needle whose eye may be opened for threading (FIG. 25), closed for tufting (FIG. 25A), and opened for release of a loop tuft (FIG. 25B);

FIGS. 25C and 25D are front elevational views of another form of split-tip needle whose normally closed eye (FIG. 25C) may be opened (FIG. 25D) for threading and/or release of a loop tuft by a rotatable cam;

FIG. 25E shows, in section, various suitable shapes for the rotatable cam of FIG. 25C;

FIG. 26 schematically and partly in section illustrates a tufting station using a reciprocable split-eye needle for making loop-tufts from a continuous strand by which it is threaded in each cycle of reciprocation;

FIG. 26A schematically and in perspective shows strand-clamping mechanism suited for FIG. 26 and FIG. 27;

FIG. 26B schematically and in perspective shows strand-guide means suited for the tufting station of FIGS. 26 and 27;

FIG. 27 schematically and partly in section illustrates a tufting station generally similar to FIG. 26 and additionally including a strand-selection and strand-cutting arrangement similar to FIG. 10A;

FIG. 28 schematically and partly in section illustrates a tufting station using rotary anvil/rotary blade means for making loop-tufts from a continuous strand;

FIG. 29 schematically and partly in section illustrates a tufting station of type shown in FIG. 28 but preceded by a multi-strand selector of type shown in FIGS. 10A and 27;

FIG. 29A is a detail view of a strand-guide block shown in FIG. 29.

FIG. 30 schematically and partly in section illustrates a tufting station of type shown in FIGS. 28,29 but additionally including knife means in certain recesses of the anvil for cutting loop-tufts;

FIG. 31 is a fragmentary view, on enlarged scale, illustrative of cutting of tuft-loops by blade and knife means shown in FIG. 30;

FIG. 32 is a perspective view showing a multiplicity of tufting stations such as shown in FIG. 30;

FIGS. 33A-33D are perspective views, on enlarged scale, of tufting blades having different edge configurations;

FIGS. 34 to 36 are sectional views taken on the line 34-34 of FIG. 30 showing tufting blade /recess relation for obtaining tuft-loops of equal height (FIG. 34), tuft loops of different heights (FIG. 35) and cut loops, uncut loops, and loops of different height (FIG. 36);

FIG. 37 is illustrative of a modification of FIG. 30 in which the tufting blades are moved radially, as well as angularly, into and out of recesses of the rotary anvil means;

FIG. 38 is a fragmentary view, on enlarged scale, of a modification of FIG. 37;

FIGS. 39, 39A and 40 are perspective views of other modifications of rotary anvil/rotary blade tufting arrangement of FIG. 37;

FIGS. 41, 41A and 42 are fragmentary views showing various presser-foot ring arrangement for the rotary anvil/rotary blade tufting arrangement;

FIG. 43 is a fragmentary sectional view, in front elevation and on enlarged scale, showing tufting blade, presser-ring and anvil elements suited for the multi-station tufting arrangement shown in FIG. 40;

FIG. 44 is an end elevational view, partly in section, of elements shown in FIG. 43;

FIG. 45 is a perspective view of another modification of FIG. 30 in which the tufting blades are reciprocable;

FIG. 46 is a perspective view showing a multiplicity of tufting stations similar to FIG. 45;

FIG. 47 is a modification of FIG. 46 in which the rotary anvil presents a flat-sided surface with recesses both lengthwise and crosswise of the backing for formation, by an array of reciprocable tufting knives, of tufting loops both lengthwise and crosswise of the backing;

FIG. 47A, 47B and 47C are explanatory schematic Figures referred to in discussion of FIG. 47;

FIGS. 48 and 49 are modifications of FIG. 47 in which the tufting anvil is of belt type;

FIG. 50 is a modification of FIG. 32 using a belt-type anvil;

FIG. 51 is a modification of FIG. 40 using a belt-type anvil;

FIGS. 52 and 53 are fragmentary views showing, on enlarged scale, constructional details of two forms of belt-anvil, and

FIG. 54 is a fragmentary view showing a modification of the multi-blade arrangement of FIG. 47A.

SUMMARY OF THE INVENTION

In accordance with one aspect of the invention, the tufting needles are of split-eye type having two shank members which form an elongated eye which can be opened at or near the needle tip under control of cam means which engages either or both shank members. In some forms of these split-eye nee-

dles used to apply bits as U-tufting, the needle-eye may be opened to facilitate threading; in some forms of these split-eye needles used to apply bits as loop-tufting, the needle eyes are opened for release of a tuft loop; in some forms of these split-eye needles used to apply bits as U-and/or loop-tufting or to apply a continuous strand as a series of loop tufts, the needle eyes may be opened both for threading and for release of loop-tufts: in still another form, the needle-eye is opened for threading and closed to expel a loop-tuft whether formed from a bit or a length of continuous strand. The split-eye needles may be ganged with closed-eye needles in various arrangement to form hybrid tufting.

In some forms of the invention, the backing and strands of tufting material are passed between anvil means and cutter means, either or both of which may be of rotary type, belt type, or reciprocating type. In all cases, the anvil means has spaced recesses and the cutter means has spaced tufting blades which slit the backing to enable the blades to force the strands through the slits into recesses of the anvil means, thus to form loop-tufts projecting from one side of the backing with adjacent tufts connected to one another on the other side of the backing between adjacent slits. Any one or more of the anvil recesses may be provided with knife means to cut the loop-tufts for conversion, for example, to U-tufts, or such knives may be omitted: hybrid tufting may be produced by providing some anvil recesses with knife means — the other anvil recesses having no knife means or disabled knife means. Either the rotary anvil means or the rotary cutter means may have spaced presser-foot rings which press the backing against the other means, in the paths of the tufting blades. In general, the individual tufting blades are of forked-end construction, each having spaced tips to slit the backing and force a strand disposed between the tips through the slit backing. In some modifications in which the anvil means and the cutter means are of rotary type, they serve as feed-rolls for the backing. In other modifications in which the tufting blades are reciprocable, the backing is fed with superimposed strands between the blades and the anvil means by a separate step-by-step mechanism. In some modifications of the rotary anvil/rotary tufting blade type, the tufting blades are fixedly mounted to extend a fixed distance from the axis of rotation; in other modifications of the rotary anvil/rotary tufting blade type, the tufting blades are moved radially of their axis of rotation as they rotate into and out of the anvil recess, thus to permit formation of higher loop-tufts and/or closer spacing of successively formed tufts without danger of damage to or breakage of the blades.

In accordance with another aspect of the invention, the tufting stations may be preceded by at least one rotary cutter as the strand-severing means. In modifications which provide for strand-selection, or for bit-length selection, or for both strand-selection and bit-length selection, there is used a plurality of rotary cutters, each with its individual anvil whereas in other modifications providing for strand-selection, or for bit-length selection, or for both strand-selection and bit-length selection, a single anvil serves a plurality of rotary cutters. The anvil, as well as the cutter, may be rotatable to form a pair of nip-rolls for feeding a measured length of strand to be detached as a bit. In rotary cutter-bar/anvil arrangements used for cutting bits from a strand, a plurality of knives having the same peripheral spacing may be used, the spacing of the knives predetermined the length of successive bits. Selection of different bit-lengths may be afforded by use of different rotary-cutter bars having different number of knives per set, or by changing the number of knives per set of the same cutter bar. The corresponding knives of different sets for supplying bits to different tufting stations may be in axial alignment along the cutter bar or may be angularly offset along the cutter bar to provide different overall patterns of the applied tufting. In some modifications, the spacing between the knives of a set automatically sets a bit-stop which arrests the leading end of a discrete bit or a bit-length of as yet uncut strand in position for threading of the associated tufting-needle means. In most modifications, the

transport of tufting yarn to the rotary cutter and from the rotary cutter to the threading station is effected by flow of gas, specifically air, in an air-flow passage. In some modifications, the individual knives of a rotary cutter-bar are radially slideable and each has its own reaction spring to predetermine the strand-cutting pressure whereas in other modifications, the knives of a rotary cutter-bar are rigidly mounted and the cutting pressure for all knives is predetermined by applying fluid pressure to the floating shaft of the cutter bar or its associated anvil.

In some modifications of the invention in which the tufting is applied to the backing as discrete bits, the transport of tufting yarn to the threading station is effected by flow of gas which leaves the yarn passage through a tubular bit-stop; for a tubular bit-stop of rigid material, the tube is of bore smaller than the yarn to provide a constriction arresting the yarn end; for a tubular bit-stop of elastomeric material, it is squeezed to form a constriction arresting the yarn end. In some modifications of the invention, the distance of the bit-stop constriction from the tufting needle is controlled, manually or automatically, by a cam which either adjusts the position of a rigid stop or the position at which an elastomeric tubular stop is squeezed.

Further in accordance with the invention, various strand-restraining means are provided to prevent undesired movement of a strand of tufting material. In modifications of the invention in which each of one or more strands is associated with an individual rotary-cutter/anvil means, the rotary-cutter/anvil means itself may also serve, when at rest, as a strand-clamp or stop. In modifications of the invention in which any of several strands is to be fed to a common rotary-cutter/anvil means, the non-selected strands are restrained by separate means in advance of said rotary-cutter/anvil means. In some modifications in which the strands are gas-flow transported via respective rigid-wall passages, the transport of non-selected strands is precluded by selectively operable plungers intercepting their passages. In some modifications in which the strands are gas-flow transported via respective elastomeric wall-tubes, the transport of non-selected strands is precluded by selectively operable tube-squeezing means. In some modifications in which the strands are gas-flow transported via respective passages, the transport of non-selected strands is precluded by one or more partial locking turns thereof about their respective rotatable selector spools, the selected strand being unwound from its selector spool and passing freely along the corresponding flow passage. In some modifications of the invention involving formation of loop tufts from a continuous strand, an intermittently operable strand-clamping means beyond the tufting needle means clamps the strand to prevent its retrograde movement while the next loop is being formed.

In all modifications of the invention involving tufting of discrete bits cut from a strand of tufting material, the transport of the strand to and beyond the rotary-cutter/anvil means is effected, at least in part, by flow of air or other gas. In some modifications of the invention involving tufting from a continuous length of a selected strand, the transport of the selected strand to the rotary-cutter/anvil means is effected by gas-flow; beyond the rotary-cutter/anvil means, the transport is effected mechanically, as by mechanism including nip rolls.

In all modifications of the invention having reciprocating needles or blades, the extent to which the backing is advanced per cycle of the tufting-needle means may be changed by varying the stroke of the oscillatable arm of a clutch in order to select the number of rows of tufts per unit of running length of the tufted product. Also in all modifications, the lateral position of the tufts of one row may be shifted with respect to tufts of a different row. Preferably, and to that end, at least one roll which engages the backing across its width is movable axially, as by cam means operating in timed relation to the needle bar. Alternatively, the needle bar and associated strand-severing and transporting means may be shifted laterally of the direction of advance of the backing.

The invention further resides in features of construction, combination and arrangement hereinafter described and claimed.

DETAILED DESCRIPTION

Referring to FIG. 1, the basic mechanism associated with an individual tufting station 10 comprises a dual needle 11, a rotary cutter-bar/anvil arrangement 12 and a gas-flow transport means 13. The backing L, of burlap, woven or non-woven plastic or fabric, or other web of backing material is advanced step-by-step by a web feed and guide system 14 including the rolls 15A, 15B. It is, of course, to be understood that for manufacture of tufted products, such as carpets, rugs, drapes, tapes- 10 tries, upholstering fabrics, wall and automobile interior coverings, and the like, the tufting machine comprises a multiplicity of such stations whose needles may be attached to a common needle bar 8.

The dual needle 11 is reciprocated by means including the 20 needle bar cam 16 on a one-time shaft 17 of the tufting machine. Upon completion of a tufting stroke, the dual needle 11 is in its uppermost or retracted position (FIG. 1B) for which it is in the clear well above the backing L. The stripper bar 36 (FIG. 1) holds the backing L down while needle 11 is 25 moving upwardly through the backing to form a U-tuft, as later described. While the needle is retracted, the backing L is advanced one step in the direction of the feathered arrow (FIG. 1B). As the needle 11 descends toward its threading position (FIG. 1), the tip ends of the needle pierce the now stationary backing L and pass into the bit-delivery end or bit-loading station of the pneumatic transport means 13, in order to bring both eyes of the dual needle 11 into alignment with the passage 19 of the pneumatic transport system.

With certainty to insure threading for various sizes and 30 compositions of the strand S of tufting material, each needle element 18 of the dual needle 11 may have separable shank or leg components 18A, 18B (FIG. 1A). Normally, the lower free ends (FIG. 1C) of legs 18A, 18B of each needle 18 are in position to form an elongated closed eye 9. Preferably, and as shown, the lower free end of the longer leg 18A is hook-shaped to form the tip T of the needle and the bottom of the needle eye 9.

At the bit-loading or threading position, the needle legs 40 18A, 18B are spread apart (FIG. 1A) in order that the now open or enlarged eye 9 is able, with certainty, to receive and pass the leading end of a strand bit B as propelled from the bit-cutting mechanism 12 via the gas-flow transport structure 13 (FIG. 1). An arrangement for effecting such temporary widen-

50 ing of the needle eye 9 comprises a cam or wedge 20 which, in this modification, extends into or through the eye 9 and is normally clear of the legs 18A, 18B (FIG. 1C). Suitably below the top of the eye formed by them, the inner or adjacent faces of the legs 18A, 18B are shaped to form converging cam-surfaces 55 21U, 21U. As the needle moves from its retracted position (FIG. 1C) to its bit-loading or threading position (FIG. 1A), the wedge 20 is engaged by these cam-surfaces 21U of the legs 18A, 18B. In consequence, the lower portions of both legs are displaced outwardly, thus widening or opening the eye 9 near the needle tip to afford desired clearance for an incoming bit of tufting material. As the loaded double needle 11 moves upwardly towards the retracted position (FIGS. 1B, 1C), the cam-surfaces 21U, 21U of both needle elements leave the

60 wedge cam 20, thus permitting the lower ends of both pairs of legs 18A, 18B to return to their normal position, consequently closing the eyes 9 before the hook end of leg 18A passes upwardly through the backing L to apply a bit (FIGS. 1B, 1C) as a U-tuft. Preferably, and as shown, a slight clearance or gap is 65 provided at the lowermost end of leg 18B (FIG. 1C) to prevent clamping of any tendrils of a bit as the eye closes.

The mechanism 12 for feeding the strand S from a supply spool SS (FIG. 1) and for cutting bits B therefrom comprises a pair of rolls or discs 22, 23 coupled for rotation in opposite 70 directions. In the particular construction shown in FIG. 1, the

upper roll 22 is provided with a set of projecting knives 24A et seq. spaced about the periphery of the roll in order to form a rotary cutter bar as well as a feed roll. The lower roll may be provided with recesses or grooves 25A et seq. which serve as anvils for the knives 24A et seq. Thus, the lower roll 23 serves both as a rotary anvil as well as a feed roll. The grooves 25A et seq. (FIG. 1) are of suitable shape, for example, curvilinear (FIG. 2A), in turn to cooperate with the knives 24A et seq. (FIG. 1) in cutting a bit and controlling the leading end of strand S.

The rolls 22,23 turn in unison in opposite directions, as indicated by the arrows, and are driven by any suitable means (not shown) in timed relation to the reciprocating needle 11. For the position of rolls 22,23 shown in FIG. 1, the lowermost knife 24B has just completed severance of the trailing end of a bit B whose leading end was cut by knife 24A in the preceding cycle of reciprocation of the needle. Before the needle again returns to its bit-loading position (FIGS. 1,1A), the new leading end of strand S is fed by rolls 22,23 to project into the inlet end of the transport passage 19. When the needle 11 has again returned to the bit-loading position shown in FIG. 1, the next knife 24C of cutter bar 22 cooperates with the next groove 25C of the rotary anvil 23 to cut another measured bit from the leading end of strand S.

In turn, each detached bit is propelled by air or other suitable gas along passage 19 and passes endwise through the eyes 9 of the dual needle 11 until its leading end is arrested by stop 26 beyond the needle. The stop 26 may be positioned in order that the loaded bit, as threaded into the needle, extends substantially equally on both sides of dual needle 11 (FIG. 1), or alternatively may be made to extend unequally on both sides of the needle. The propulsion of a bit from the stand-severing arrangement 12 is effected by flow of air or other gas from the bit-receiving end of passage 19 to and beyond the confined region into which the needle 11 is inserted for loading. As shown, the stop 26 may have a bore 19A which serves as a continuation of passage 19 for flow of air. However, a barrier, such as the end constriction shown, at or near the inlet end of passage 19A provides the bit-arresting function of stop 26. For pneumatic transport of the bits in passage 19, an above-atmospheric pressure source may be connected to that passage upstream of the needle or a below-atmospheric pressure source may be connected to passage 19 downstream of the needle. For various reasons, it is preferred that the bit be transported by air flowing to a below-atmospheric pressure source downstream of the needle-loading zone of passage 19. For such purpose, the outlet end of passage 19A of stop 26 has a fitting for connection, via tube 28, to a suction pump or other source (not shown). Such suction pump may be connected to passage 19 beyond the needle 11 in other ways, such as via a manifold common to the outlet ends of all passages 19 of the tuft-applying stations. For economy of air or other gas, its flow may be controlled by valve means 28V timed to open as the strand end is being fed and cut and to close after positioning of a bit at the threading station.

Each needle 11 may remain at rest in the bit-loading position for a time sufficient to permit pneumatic transport of a bit from the strand-severing arrangement 12 and for threading of the transported bit as positioned by stop 26 into the needle. This Down-dwell of the needle 11 (FIG. 1) may be predetermined by the dwell sector 16D of the needle-bar cam 16. In the particular construction shown by way of example, the dwell sector 16D is about 45°, which affords sufficient time for bit-transport and threading not only for one measured length of bit but for a substantial range of measured bit-lengths which require corresponding different peripheral spacings of the cutter-bar knives and different settings of bit-stop 26. In general, the phasing of cam 16 with respect to the rotary cutter bar and anvil arrangement is such that the shortest bit is cut at, or just after, the beginning of the Down-dwell, and the length of the dwell sector 16D is sufficient to afford the required transport and bit-threading time for the longest bit whose severance occurs later in the Down-dwell period of the needle cycle.

At this point, it may also be noted that the cam 16 has a second dwell sector 16U (FIG. 1B) which provides that the needle 11 remains in full retracted position for a substantial fraction of the needle-bar cycle in order to afford a longer time in the needle cycle for indexing of the backing. The dwell sector 16U may be about 90° in extent. Particularly, when as later discussed in connection with FIG. 7 there is provision for changing the indexed advance of the backing L, the phasing of the needle-bar cam 16 is such that the Up-dwell of the needle is centered (FIG. 7A) with respect to the feeding interval of the backing L.

In the modified form of tufting needle shown in FIG. 1AA, an external cam 20A is used to open the needle eye for threading. As each needle 18A of the dual pair 11 approaches the threading position, cam 20A engages the external cam-surface U21 of leg 18B to press it toward leg 18A, thus to open the eye above the hooked tip T. As the needle ascends, the bit B is caught by the hooked tip T and leg 18B, which under control of cam 20A, moves away from leg 18A to close the eye before the hooked tip passes upwardly through the backing to apply the bit as a U-tuft.

A modified form 26A of the bit-stop 26 of FIG. 1 is shown in FIG. 1D. In this modification, which can be incorporated in the basic mechanism of FIG. 1, the bit passage beginning just beyond the needle 11 (FIG. 1D) comprises the internal bore 19A of a deformable resilient tube 28A of natural or synthetic rubber, other elastomeric material, or the like. The tube 28A extends beyond two squeezing or clamping members 29A,29B. The upper clamping member 29B of rectangular, round or other cross-section, may be stationary. The lower clamping member is movable and may be a cam or eccentric 29A rotatable about a fixed axis to select the distance from needle 11 at which the bit-passage 19A is constricted by the squeeze members 29A,29B sufficiently to prevent further movement of a bit as transported by a flow of air. The bit is stopped by such constriction, but the air may continue its flow. With this form of stop, there is reduced tendency for the bits to bounce back from the stop. This type of constriction serves both as a stop and a brake. In the particular construction shown in FIG. 1D, the movable squeezing member 29A may have three lobes and may be moved or indexed to corresponding angular position by correspondingly shifting the location of the constriction of tube 28A to suit measured bits cut to different lengths. Also, the entire cam mechanism may be shifted, if desired, horizontally for one or more other ranges of minimum to maximum strand-lengths.

In the particular arrangement shown in FIG. 1 by way of example, the cutter bar 22 is shown as having a set of eight knives equally spaced at 45° intervals. To provide the needle 11 with a bit each time it arrives at bit-loading position, the roll 22 is moved one-eighth revolution per cycle of the needle. To cut shorter or longer measured bits, different cutter bars 22 with correspondingly greater or lesser number of knives per set may be used with a corresponding change of the extent of angular motion of roll 22 per needle cycle. The knives 24 may be of removable type such as shown, for example, in FIGS. 2,2A and the cutter bar may be provided with a number of angularly spaced blind holes 30 sufficient to accommodate the greatest number of knives and peripheral spacings to be used; for example, the cutter bar of FIG. 1 may have eight holes 30 (FIG. 2A), each slidably to receive the shank 31 of a knife 24 (FIG. 2). The shank 31 has a slot 32 which, with the knife 24 in position in hole 30, receives a fixed stop pin 33 (FIG. 2A) which passes into cross holes of the cutter bar 22. A reaction spring 35 in the bottom of hole 30 forces the knife outwardly to a projecting position defined by engagement of pin 33 with the inner end of the shank slot 32. During cutting of a strand, the knife is forced inwardly of the cutter bar in opposition to the counterforce of spring 35.

With the particular cutter bar construction shown in FIG. 1, eight holes 30 permit insertion of as many as eight knives (of type shown in FIGS. 2,2A) with 45° spacing for short bits, four 75 knives for the double-length measured bits, and so on.

In any event, the cutter bar 22 may extend across the tufting machine, i.e., widthwise of the backing to supply bits for a multiplicity of tufting needles and may be either a series of discs, each having its own set of knife, for cutting bits of the same or different measured lengths, or may be a continuous roll with knife means for cutting bits of the same or different lengths.

Specifically as indicated in FIG. 21, the cutter bar 22 may be a series of discs 37A et seq., each with its own set of knives for supplying bits to a corresponding tufting station. The number and spacing of the knives may be the same or different for different discs. Also as later explained in discussion of FIGS. 3,3A; 4,4A, the knives of different discs may be in axial alignment or angularly offset. Either relationship is obtainable by suitably, angularly orienting the discs before locking them in position to form a multi-station cutter bar.

The cutter bar 22 may also be an elongated continuous roll 38 (FIGS. 21A,21B) or a series of such rolls with slots for receiving knife elements and/or spacers. By use of knives and spacers of selected lengths, there is afforded a wide range of choice of the measured bit-lengths supplied by the roll 38 to the corresponding group of dual tufting needles 318A-318N (FIG. 21A). When all needles of the group are to be supplied with bits of the same length (FIG. 21B), a single set of knives without spacers may be used.

With the corresponding knives of all sets in alignment axially of the multi-station cutter bar (FIG. 3), all needles may receive a bit per needle-bar cycle and the resulting tufting pattern is exemplified by FIG. 3A. Specifically, each of the rows R1 et seq., as in turn applied lengthwise of the manufactured product, has an applied bit for each linear line or column C1 et seq. widthwise of the product. This relationship remains the same whether there are eight, four or other knives per set provided that the cutter bar timing is such that the needles of the different stations receive a bit per needle-bar cycle.

Variations of the pattern are possible by angularly offsetting the knives of the different sets. For example, with the corresponding knives of adjacent sets angularly offset by half the angular spacing of the knives of a set (FIG. 4), the length of the applied bits is doubled, the number of bits per row is reduced by a factor of 2, and the bits of adjacent rows are staggered (FIG. 4A). Thus, for example, a change from the pattern of short bits (FIG. 3A) to the more open pattern of double-length bits (FIG. 4A) requires only the substitution of a cutter bar having the knife arrangement of FIG. 3 to one having the knife arrangement of FIG. 4.

For positioning bits of different lengths, the bit-stop 26 of FIG. 1 may be cam-operated as shown in FIG. 5. For example, to accommodate three different bit-lengths, the cam 40 has three lobes 40A,40B,40C for selective engagement with the cam-follower 41 on stop 26. With the lobe 40A engaging cam-follower 41 (FIG. 5), the stop 26 is held in its short-bit position against the reaction of spring 42; with cam 40 rotated to effect engagement of its lobe 40B with cam-follower 41, the stop 26 is in its intermediate-bit position; with cam 40 rotated to effect engagement of its lobe 40C with cam-follower 41, the stop 26 is in its long-bit position. With the knives of a set spaced to cut bits of any one of three lengths, the cam 40 may be manually indexed to the corresponding lobe position; alternatively, the indexing may be effected automatically, as by a pattern-controlled actuator, not shown. These three stop positions may correspond to the different bit-lengths corresponding with the knife settings shown in FIGS. 6, 6A and 6B; if desired, the bit-lengths need not be centered when in the eyes of the needles.

When the knives of a set are unequally angularly spaced, repeatedly to cut a sequence of three different bit-lengths (FIG. 6C), the operating shaft of cam 40 (FIG. 5) or the operating shaft of cam 29A (FIG. 1D) is synchronized with rotation of the cutter bar 22 by any suitable means, repeatedly to vary the position of the bit stop 26 to correspond with the bit-lengths. With such arrangement, the pile height varies on the face of the rug, carpet or other tufted product.

To vary the number of rows per unit of running length of the tufted product, provisions may be made to change the extent to which the backing L is advanced per cycle of the tufting needles. The driven element of a Form Sprag or other one-direction clutch 45 (FIG. 7) may be coupled to the feed roll 15B (FIG. 1) for the backing L, and the drive element of the clutch is connected to an oscillatable arm 46 (FIG. 7). A slot in arm 46 receives the pivot block 47 which may be adjusted to and held in fixed position, as by locking means 47A, at any desired distance from the rotational axis of the feed roll. A link 48 couples the pivot block 47 to the crank pin 49 on a drive shaft 50 which makes one revolution per cycle of the needle bar. By selective adjustment of the pivot block 47, the arc through which the clutch-arm 46 is oscillated can be changed correspondingly to vary the distance between the rows of bits applied lengthwise of the backing L.

As previously mentioned and as shown in FIG. 7A, the time during which the needle bar is at rest in its up-position is at least approximately centered with respect to the time during which the driven element of clutch 45 (FIG. 7) is moved to advance the backing L. It is thus insured that for all positions of the adjustable pivot block 47 for different amounts of indexed feed of the backing L, the needle 11 is clear of the backing L (FIG. 1B) during feeding movement of the latter.

In the production of shag rugs, the pivot block 47 (FIG. 7) may be set to effect relatively large indexed advance of the backing L per needle-bar cycle, the cutter bar 22 selected to have correspondingly large angular spacing between the knives of each set (FIG. 6B, for example), and the bit stops 26 (FIGS. 1, 1D, 5) are correspondingly set to position long tufting bits. The knives of adjacent sets may be offset as in FIG. 4, so that each tufting needle applies a bit in alternate cycles rather than in every cycle to produce a tufting pattern similar to FIG. 4A but with greater distance between the tufting rows.

Provision may also be made laterally to change the position of the backing L relative to the tufting needles in intervals between successive movements of the needles to the threading position. Specifically the roll 15B of FIG. 1 may be replaced by a roll 15C (FIG. 8), for example, by a Thompson linear bearing, for free movement axially of its axis of rotation, and roll 15A of FIG. 1 is replaced by an axially movable roll similar to roll 15C (FIG. 8), but having no spikes. A peripheral series of spaced cam-follower 55 at end of the roll 15C engages a barrel cam 56 rotated in timed relation to the needle bar. In the intervals for which the tufting needles are clear of the backing L, this pair of linearly-reciprocable rolls, in position corresponding with rolls 15A,15B of FIG. 1, move laterally of the needle bar in order that bits applied to it in successive cycles are in different positions crosswise of the backing L.

As shown in FIG. 9, the basic mechanism of FIG. 1 may be modified to provide for supply to the bit-loading station of bits which may differ in length, color, or both. To that end, the bit-transport passage 19 to the tufting needle 11 is in communication with a plurality of cutter-bar arrangements 12A et seq. which respectively cut bits from the strands SA et seq. of tufting material. For a given cycle of the needle 11, any selected one of the normally inactive cutter bars 22A et seq. may be coupled to a drive via one of the magnetic clutches 60A et seq. to detach a bit from a corresponding one of the strands SA et seq. Automatic programming of the clutches 60A et seq. may be obtained by any known means including conductive patterns, punch cards, magnetic or optical tapes and the like.

First assuming that the strands are of the same color, the angular spacing of the knives may differ for different cutter bars. Consequently, in any cycle of the machine, the length of the bit delivered to the tufting needle via one of the passages 63A et seq. (FIG. 9) depends upon which of the cutter bars 22A et seq. is selectively operated in accordance with the pattern program. The position of the associated bit-positioning cam 40 may also be automatically controlled correspondingly to set the stop 26 to position the selected bit-length. For a single color, five-length selection, the cam 40 would have five lobes

for positioning of bits having three different lengths. The machine shown may thus produce sculptured rugs or carpets whose pattern requires five or less different pile heights: to adapt the machine for a greater number of available bit-lengths, the number of cutter-bar/anvil means is correspondingly increased.

With the five-cutter bar arrangement 12A to 12E shown in FIG. 9, the strands SA to SE may each be of different color so that in any cycle of the machine the color of the bit delivered to tufting needle 11 depends upon which of the clutches 60A to 60E is energized. The machine (FIG. 9) may thus produce any desired pattern of five or less colors, and if desired with bit-lengths equal or different for the different colors. It is to be noted that the invention is not limited to five bit-lengths or to five colors; as many of each may be used as desired. For patterns having less than five colors, for example, bits of the same color but of different length can, of course, be obtained by having strands SB, SD, for example, of the same color, and by having different peripheral spacing for the knives of the associated cutter bars 22B, 22D. It will be understood that for positioning bits of different chosen lengths, the cam 40 will have a corresponding number of lobes: for example, the three-lobe rotatable cam 40 of FIG. 9 provides for positioning of bits having three different lengths. The rotatable cam 40 may be replaced by a linear cam which can provide a very large number of displacements or lobes.

An arrangement for automatically changing the setting of the individual bit-stops 26 is shown in FIG. 9A. Each of cams 40 is attached to a gear 42 to form an assembly free to rotate on the stationary shaft 43. The gear 42 is in mesh with a gear 51 which is free on the rotating shaft 52. Gear 51 is mounted on or attached to the driven element of a magnetic clutch 53 whose driving element rotates with the shaft 52. The clutch gimbal 54 may provide one electrical connection to the magnetic clutch 53 and the other electrical connection may be provided via shaft 52 which is grounded. Selective energization of the clutches 53 for the bit-stops of the various tufting stations may be afforded by any suitable programming arrangement including those specifically hereinbefore mentioned.

It is also to be noted that the cams 40 may be left set at one position for different bit-lengths of the same or different colors so that, for example, tufts from one bit-length will have legs of equal length and tufts from other bit-lengths will have legs of unequal length. If it is desired to make the entire rug substantially of tufts not centered in the needles, the stop cams 40 may be positioned or changed so that the bits of the same or different color as threaded are in predetermined non-centered position in the needles.

In the modification of the basic mechanism shown in FIG. 10, the bits successively delivered to the tufting needle 11 may be of different colors. In this modification, a single set of knives 24 is used per tufting station and the length of the bits cut from a selected strand depends upon the predetermined peripheral spacing of the knives as explained in discussion of FIGS. 6A-6C. For the five-color selective arrangement shown in FIG. 10, for example, any of the strands SA to SE may be selected for pneumatic transport to the nip of the feed rolls 22, 23 by pressurized air supplied via inlet tubes 73A-73E to the respective strand passages 63A to 63E of the block structure 64 or equivalent. Normally, all of the strands SA to SE are held in the respective flow passages 63A to 63E as by a solenoid-operated plunger or equivalent device, such as for example an air-cylinder. Specifically and as shown in FIG. 11, the plunger 65C has been retracted by energization of a normally deenergized solenoid 66C to release the selected strand SC for pneumatic transport in passage 63C. Upon deenergization of the solenoid, the plunger 65C is returned to its clamping engagement with strand SC by suitable reaction means, such as spring 67C, and remains in such position until its solenoid is again energized under control of a programming arrangement of any suitable type. Alternatively, of course, a normally energized solenoid may be used to hold plunger 65C in clamped

position, in which case a reversely acting spring retracts the plunger upon deenergization of the solenoid. The clamping devices for the other strands are of similar construction, and similarly controlled for production of tufted products whose pattern requires, for example, no more than five colors as afforded by the particular strand-supply arrangement shown in FIG. 10. Obviously here and in FIG. 9 as well, a greater range of color selection may be afforded by correspondingly increasing the number of strand passages, but unlike the FIG. 9 arrangement, it is not necessary to increase the number of bit-severing mechanisms: in FIG. 10, a single rotary-cutter/anvil means serves as the severing means for all strands.

The block structure 64 of FIG. 10 which provides the strand passages, and the strand-clamping plungers which must enter those passages, may both be replaced by an array of deformable resilient tubes of natural or synthetic rubber, other suitable elastomeric materials, or the like, which may be squeezed to clamp the non-selected strands. Referring to FIG. 12, the strand/air passage 63C, for example, is the internal bore of tube 70C which extends between a pair of squeezing members 71C and 72C. One of these members, for example, lower member 72C, may be fixed, and the other movable. In their normal position (FIG. 12), the squeeze members 71C, 72C deform the tube 70C to clamp the strand SC and thereby prevent movement of the strand by air supplied via tube 73C. When a corresponding solenoid 66C, or equivalent actuator, is selected, the upper member 71C releases the strand SC, permitting it to move to the bit-severing mechanism 12 (FIG. 10).

The modification shown in FIG. 10A is similar to that of FIG. 10 in that only one cutter bar 22 is required per tufting station in a multi-strand selector arrangement. In FIG. 10A, the arcuate periphery of collimator block 64A is recessed to support, for rotation relative thereto, a ring-gear segment 90 whose external teeth are in mesh with the gear 51A attached to the driven element of a magnetic clutch 53A. The driving element of the clutch is fastened to the shaft 91 which, during a cycle of the needle bar, rotates in opposite directions as later described. The stationary collimator block 64A also supports a group of spools 92A et seq., each for rotation about its own axis. Each spool has a gear 93 in mesh with the internal teeth of the ring gear 90. Each of the spools has a cross-passage 95 extending therethrough. As discussed below, such cross-passage 95 of each spool comes into alignment with a corresponding one of the passages 63A et seq. of the collimator block 64A. All of passages 63A et seq. have a common outlet port close to the nip of the rotary-cutter/rotary anvil means 22, 23.

For clarity of explanation, it is assumed that the ring gear 90 has an index I which in FIG. 10A is shown opposite the 0 mark of a stationary scale. For this zero position of the ring gear 90, the passage 95 of spool 92C is in alignment with collimator passage 63C and the strand SC extends freely through the spool passage into passage 63C (see line 3, column SC of TABLE A below) for pneumatic transport of that strand to the cutter bar; all of the other strands (see line 3, columns SA, SB, SD, SE of TABLE A) are restrained from movement because these spools have one or more turns wound thereon in clockwise or counterclockwise direction.

TABLE A

SELECTED STRAND

Segment Position	SA	SB	SC	SD	SE
70	Free	1-CC Turn	2-CC Turn	3-CC Turn	4-CC Turn
	+ 1	1-C Turn	Free	1-CC Turn	2-CC Turn
	0	2-C Turn	1-C Turn	Free	1-CC Turn
	- 1	3-C Turn	2-C Turn	1-C Turn	Free Turn
75	- 2	4-C Turn	3-C Turn	2-C Turn	1-C Turn Free

C = Clockwise
CC = Counterclockwise

So long as strand SC is to be fed to the associated tufting station in subsequent operation of the machine, the gear 90 of the strand-selector unit remains decoupled from shaft 91 because of continued deenergization of clutch 53A.

Assuming it is desired to change from feed of strand SC to feed of strand SB to meet a change in the tufted pattern demand, the clutch 53A is energized during clockwise rotation of shaft 91 and for an interval suited to move gear-segment 90 from its 0 position to its +1 position. As a result of such movement, all of the spools rotate one revolution in counterclockwise direction. The rotation of spool 92C winds one counterclockwise turn of strand SC on that spool (line 2, column SB of TABLE A) and thus retracts the leading end of strand SC back into passage 63C to clear the common exit throat of all passages 63A et seq. At the same time, the counterclockwise rotation of spool 92B unwinds the strand SB one turn so that it extends freely and directly through passage 95 of that spool into passage 63B. Thus, all strands except strand SB are restrained against their feeding movement by air flowing through all passages 63A et seq. toward the cutter bar (see line 2, columns SA, SC, SD, SE of TABLE A). Strand SB is pneumatically fed to the cutter bar 22. By the time a bit has been cut from the newly selected strand, the needle has arrived at the threading station in position to be threaded by that bit. As soon as that bit has been cut off, the selector mechanism is ready, whenever required, to change to still another strand.

In like manner, and as should be clear from TABLE A, any one of the strands SA et seq. may be selected for feed to the cutter bar 22 in any one or more cycles of the tufting machine. As in the other strand-selector arrangements, the strands may be of any different characteristic, such as color, material, thickness and so forth. Also as in other modifications, the strand-selectors are units for individual tufting stations and may be individually controlled or programmed to provide a desired pattern in the tufted product. In FIG. 10A, the clutch 53A may be the programmed control-device for strand-selection.

In the previously described cutter-bar/anvil arrangement, the knives are yieldingly mounted in the cutter bar disc or roll and are individually biased by spring means to provide strand/cutting pressure. Such arrangements require a multiplicity of knife-biasing springs which should be matched for uniformity of the cutting pressures of different knives. Also the cutting pressures, for clean-cutting of the strands without excessive knife-wear, should be different for different tufting materials, thus requiring different optimum knife pressures. Instead of such arrangements, there may be used a cutter bar having fixed knives and the shaft of either the rotary anvil 23 or the cutter bar 22 may be movably mounted and pressure applied thereto, as by an air motor of the diaphragm, piston or other type. The air-supply pressure for the motor may be selected or adjusted for optimum and uniform cutting pressure of all knives for any of various tufting materials. Specifically, in FIG. 13, the shaft 80 of the cutter bar 22 is movably supported by lever arm 82 which is coupled, as by link 83, to the movable output element of the air motor 81. Thus, each knife 24 as it in turn cooperates with the anvil 23 to cut the strand S applies cutting pressure determined by the air pressure supplied to the motor 81 as preselected to suit the characteristics of the strand material.

In the multi-cutter bar arrangement shown in FIG. 14, a single rotary anvil 23Z is used instead of a plurality of anvils — one for each cutter bar as in FIG. 9. The common anvil 23Z (FIG. 14) rotates continuously, but which of the strands SA to SD is fed to the associated bit-loading station depends upon which of the clutches 60A to 60D is selectively energized. For example, if clutch 60C is energized, the cutter bar 22C is coupled to its drive to cut a bit from the selected strand SC for pneumatic transport to the needle: the remainder of the cutter bars remains at rest with one of their knives blocking the feed

of the other strands to that needle. The strands SA et seq. may be of the same or different color, as in FIG. 9, and the number of knives may be the same or different for the respective cutter bars 22A et seq., also as in FIG. 9, for supply of bits of the same or different length. It may be noted that the periphery of the common anvil 23Z (FIG. 14) is ungrooved in order that any portion of its surface may serve as an anvil for the knives of the cutter bars regardless of their peripheral spacing. Ungrooved anvils may be used in all of the rotary-cutter/anvil means herein shown.

With all previously herein described forms of the present invention, the bits of tufting material as applied to the backing L form a tufted product having free-ended or U-pile whereas those now described may form a tufted product having looped pile.

For the modification shown in FIGS. 15-17, the needle 118 for each station is a single needle of split eye construction differing from that shown in FIGS. 1,1A in that the needle eye is opened when the needle is clear of the backing L rather than opened when the needle is in threading position and is provided with cam-surfaces 21L,21L for that purpose. The tip-forming ends of needle legs 118A,118B may abut (FIGS. 15B,15C) or may be complementarily notched or recessed to overlap (FIGS. 15D,15E) when in normal closed-eye position. In either case, the needle 118 is of split-tip type rather than of the split-side type (FIGS. 1A,1AA).

As shown in FIGS. 15,15A, the needle 118 has penetrated the backing L to bring its closed eye into alignment with the passage 19 of the pneumatic transport system 13. For this threading position of needle 118, the wedge 120, which extends between the legs 118A,118B of the needle, is clear of the cam-surfaces 21L of the needle legs (FIG. 15A). Consequently, the lower ends of legs 118A,118B jointly form the tip end of the needle and the lower end of the now closed needle eye (FIG. 15A). As the needle is moved upwardly toward the retracted position shown in FIGS. 16,16A, the intermediate portion of the threaded bit B is pulled through the backing L to form a loop-tuft BL, leaving the end portions of the bit on the underside of the backing L. By the time the needle 118 reaches its fully retracted position, the wedge 120 has engaged the cam-surfaces 21L of the needle legs 118A,118B, thus to spread them clear of the pile loop (FIG. 16A). The height of the loop-tuft BL may be varied in production of a sculptured article by changing the vertical position of the normally stationary wedge 120, thus to open the needle eye sooner or later in the loop-forming stroke of the needle for any preselected needle cam. The bit-length and the position of stop 26 may be correspondingly varied to insure formation of a loop of desired height and without excessive length of the bit-ends on the underside of the backing L. While the needle legs are spread apart (FIG. 16A), the backing L is advanced (FIG. 17) to carry the looped tuft BL out of the now open eye of needle 118.

Suitably beyond the needle station, the bit-ends extending from the underside of backing L may be bonded or locked to the backing by any of various known techniques. For example, a tacky liquid latex compound may be brushed or rolled onto the backing L and the tufted bit-ends, or for quicker setting, hot polyethylene or other thermoplastic cement may be spread, sprayed or rolled onto the underside of the backing L and the projecting bit-ends. In the latter case, a blast of cold air, for example, may be blown on the applied surface to chill the cement. Specifically, and as shown in FIG. 17, the bit-ends may be turned against the underside of the backing L by a cold or hot pressure roll 85 after the bonding cement has been applied. Alternatively, the roll 85 may also serve as a feed or guide roll for web or strip 86 comprising or faced with a bonding material which may be activated prior to its engagement with the backing L and the underside ends of the pile loops: in this case, the bonded material becomes a substrate of the tufted product.

A single needle of the split-side type such as shown in FIGS. 19B,19C may also be used to form a loop-tuft BL from a bit B.

The needle 618 is similar to that of FIG. 1AA except that the bit-receiving groove in the hooked-tip of the longer leg 618A is shallow. For threading (FIG. 19B), the shorter leg 618B of needle 618 is pushed, by engagement of cam-surface U21 with cam 20A, toward or against the longer leg 618A to open the needle eye at its lower end. After the threaded eye has passed through the backing L (FIG. 19C), the loop-tuft BL is swept out of the shallow groove by the shorter leg 618B during its movement to the closed-eye position under control of cam 20A.

For the loop-pile modification shown in FIGS. 18,19, the needle 211 for each station may be a dual needle with each needle 118 of the split-tip construction shown in FIGS. 15A,16A or the split-side construction shown in FIGS. 19B,19C. For this dual needle modification, each double needle 211 may form two loop-tufts from each bit (FIG. 19). For that purpose, the length of bit B supplied to a needle 211 (FIG. 18) corresponds with that length required for two pile loops, instead of one as in FIGS. 15, 19C, and the feed of the backing L, as effected by mechanism shown in FIG. 7, or its equivalent, is increased as compared to FIG. 16. The heights of the multiple loops may be varied in production of a sculptured article by changing the position of the normally stationary wedge 120, thus to open the needle eyes sooner or later in the loop-forming stroke of the dual needle. The bit-length of the position of stop 26 may be correspondingly varied to insure formation of two loops per needle stroke and without excessive length of the bit-ends left on the underside of the backing L.

In this connection, it is to be noted that the dual needle arrangement of FIGS. 18,19 may also be used to form a U-tuft (FIG. 19A) by threading the needle with a shorter bit properly positioned by adjustable stop 26. Thus, a tufting machine having dual split-tip needles 211 for its tufting stations is suited to make articles with loop-pile (FIG. 19), or with U-pile (FIG. 19A), or with both loop-pile and open-ended pile (FIG. 23A) in any desired pattern.

This concept of multiple loop formation may be extended to three or more needles having eyes which are in alignment and closed while in loading or threading position on one side of the backing L and which pull a corresponding number of loops through the backing as they move to a retracted position clear of the other side of the backing and for which all split eyes are opened to release the loops so that all loops may move with the backing as it is advanced to the new position.

Single and multiple needles of the split-eye construction shown herein may be used in other tufting machine arrangements including those shown in the aforesaid Spanel-Barton patent and the aforesaid Spanel-Brennan application.

In all the arrangements shown for applying bits to form U-pile, dual needles of the split-eye type may be each replaced by a dual or double needle 311, each of whose needles 318 has a relatively large unsplit eye (FIG. 20). Such needle is not used with a wedge (20 or 120) and has no cam-surfaces (12U or 21L). This type of needle 318 with unsplit eye may not, however, be substituted for the single needle 118 of FIGS. 15A-16A as used for making loop-pile or for the double needle 211 of FIGS. 18,19 as used for making loop-pile.

Also a needle of the closed-eye type, with an elongated eye to clear the wedge 120, may be used ahead of and/or behind needles of the split-eye type jointly to receive a bit which as applied to the backing L forms a hybrid pile element comprising one or more loop-tufts and one or more open-ended tufts. For example, as shown in FIG. 22, two closed-eye needles 518 are respectively disposed in front of and behind the two split-eye needles 118 with the eyes of all needles in alignment to receive a bit B. On the up-stroke of the needle bar, the pair of split-eye needles 118,518 forms two loops (as discussed in connection with FIGS. 18,19); the two closed-eye needles 518,518 pull the ends of the bit through the backing L to form two free-ended pile legs.

Other combinations of closed-eye needles and split-eye needles may be used to produce a tufted article having hybrid pile

for pattern contrast. For example, as shown in FIG. 23, a pair of closed-eye needles 318 may be used at any tufting station to form open-ended or U-pile BU and at least one split-eye needle 118 may be used at any other tufting station of the same machine to form loop-pile BL. As shown in FIG. 23A, a hybrid pile pattern can also be made using a dual needle in which the individual needles are of a split-eye type, such as shown in FIGS. 15A,19B and subsequent Figures, suited to free any loop-tufts that are formed. Suitably long bits may be tufted as two loops BL whereas suitably shorter bits may be tufted as a single U-tuft BU.

In the previously described modifications of the split-eye needle, the two spaced legs or shank elements extend from an integral connecting portion of the needle shank and may be biased by the resiliency inherent to such fork construction to their closed-eye or open-eye position. In the modifications shown in FIGS. 24 and 24A, the two legs 718A,718B of each needle respectively extend from two mounting elements, either or both of which may be moved to open the eye for threading, or for loop-tuft release, or for both. A single needle of such split-tip construction suffices if only loop-tufts are to be made at the corresponding station: two such needles per station provide for loop-tufting, U-tufting or both, the same as in FIGS. 19, 19A, 23A.

In FIG. 24, the legs 718A,718B of each needle respectively extend from the individual mounting members 110A,110B and are moved linearly with respect to each other to open and close the elongated needle eye formed by them. Proper alignment of the legs may be maintained by guide means exemplified by rods 111 during relative linear motion of the leg mounts 110A,110B as effected by any suitable means. For example, the two leg mounts for an individual tufting station may be forced, as by spring means not shown, to the closed-eye position of the legs 718A,718B and may be moved to open-eye position by suitably placed rotatable cam means which in another form is schematically shown in FIGS. 25C,25D. Also as shown in FIG. 24AA, the leg mounts 110A for the needle legs 718A of different tufting stations may be attached to the needle bar 8 and the leg mounts 110B for the associated needle legs 718B may be attached to the common linearly reciprocable guide bar 112 supported from the needle bar 8, as by the mounts 110A. By suitable means not shown, the bar 112 may be moved to and from the position shown in FIG. 24AA to open and close the eyes of all split-eye needles of the station. The linear motion of the bar 112 may be timed to open the needle eyes for threading, for release of loop tufts, or for both. It is immaterial which leg of the pairs of needle legs is attached to bar 112 for movement relative to the other leg.

In FIG. 24A, the legs 718A,718B of each needle respectively extend from the individual mounting members 110C,110D and are moved arcuately with respect to each other to open and close the elongated needle eye formed by them. Proper alignment of the legs may be maintained by thrust bearings, not shown, during relative arcuate motion of the leg mounts by any suitable means. For example, the two leg mounts, 110C,110D for a tufting station may be forced, as by spring means, to closed-eye position of the needle legs 718A,718B and both may be moved away from each other to open-eye position by suitably placed rotatable cam means extending between the legs, and which in another form is schematically shown in FIGS. 25C, 25D. Instead of rotating both mounts, either mount may be stationary and the other rotatable.

In both FIGS. 24 and 24A, the individual needles are of split-tip type in which the eye is open for threading, for loop release, or both, and is closed for passing through the backing. In FIGS. 24B-24D, the needle is of split-side type in which the eye is open for threading and closed for loop-tuft release and, in such respect, is similar to that shown in FIGS. 19B,19C. However, the needle legs 618A,618B of FIGS. 24B-24D are not joined by an integral shank portion but respectively extend from individual mounts 110C,110D, both reciprocable with the needle bar (not shown). In addition, the mount 110D is rotatably supported for rocking motion by any suitable means

not shown. The mount 110D is moved in clockwise direction, suitably before, or when, the needle is in threading position (FIG. 24B) to swing the leg 618B toward leg 618A, thus to open the needle eye to receive a bit B of tufting material (FIG. 24C): the mount 110D is moved in counterclockwise direction, suitably after the needle tip T has cleared the backing, to swing the leg 618B away from leg 618A, thus to sweep the loop tuft BL out of the shallow tip-groove of leg 618A (FIG. 24D).

In FIGS. 24E-24G, the mount 110D reciprocates linearly with the needle bar (not shown) but has no arcuate motion whereas the mount 110C, also reciprocable with the needle bar, is additionally rocked back and forth by any suitable means not shown. The mount 110C is moved in counterclockwise direction, suitably before, or when, the needle is in threading position (FIG. 24E) to swing the leg 618A toward leg 618B, thus to open the needle eye to receive a bit B of tufting material (FIG. 24F): the mount 110C is moved in clockwise direction, suitably after the needle tip T has cleared the backing L to swing the leg 618A away from the leg 618B so that the latter sweeps the loop-tuft BL out of the shallow tip-groove of leg 618A (FIG. 24G).

In FIGS. 24H-24J, both of the mounts 110C,110D are rotatably supported from the needle bar. The mounts 110C,110D are moved respectively in counterclockwise and clockwise directions suitably before, or when, the needle is in threading position (FIG. 24H) to swing the legs toward one another, thus to open the needle eye to receive a bit B (FIG. 24I): the mounts 110C,110D are rotated in the reverse directions, suitably after the needle tip T has cleared the backing L to swing the legs 618A,618B away from one another, thus to sweep the tuft-loop BL out of the shallow tip-groove of leg 618A.

In all of FIGS. 24; 24A; 24B-24D; 24E-24G; 24H-24J, the height of the tuft loop formed from the bit may be varied by changing the time, in the up-stroke of the needle bar, at which the loop BL is expelled (FIGS. 24D, 24E, 24J) from the needle by the arcuate motion of one or the other, or both, of the leg mounts 110C,110D. In all of such Figures, a single needle per tufting station suffices if only loop-tufts are to be formed: two such needles per station provide for loop-tufting, or U-tufting, or both, the same as in FIGS. 19, 19A, 23A.

In all of the preceding forms of the invention, the split-eye needle there shown may be replaced by a split-eye needle 411 shown in FIGS. 25-25B whose eye may be opened in one position for threading, or in another position opened for release of a looped tuft, or opened for both of those positions. Such substitution may be made, for example, in any of the dual-needle modifications of FIGS. 1-1D; 9; 10; 18-19; 22; 24; 24A; 24B; 24E; 24F; and in any of the single-needle modifications of FIGS. 15,16; 23; 24A; 24B; 24E; 24F. In other words, the split-eye needle 411 may be used to make open-end or U-tufts or loop-tufts from discrete bits of tufting as explained in discussion of the preceding modifications. As will be explained in discussion of FIG. 26, the needle 411 may also be used in individual tufting stations of a modified form of conventional tufting machine to form loop-tufts from continuous strands of tufting material, which loops, or any portion of them, may be subsequently cut if desired.

Referring to FIGS. 25-25B, the needle 411 has a split shank with legs 418A,418B. The inner faces of the legs 418A,418B are each provided with two spaced wedge-engagable or cam surfaces 21U, 21L. As the empty needle 411 approaches the backing, its cam-surfaces 21L,21L clear the double wedge 420; therefore, the free ends of legs 418A,418B engage each other to form the piercing point of the needle. When the needle tip T penetrates the backing L, the upper pair of cam-surfaces 21U,21U is engaged by cam or wedge 420, thus to spread the legs 418A,418B (FIG. 25) and open the needle eye 9 for threading by a bit B to be pneumatically fed thereto as previously described, or for threading by a bit length of a continuous strand S as later discussed. Before the needle 411 moves in reverse direction through the backing L, the wedge

420 disengages the cam-surfaces 21U,21U, thus permitting the free ends of legs 418A,418B to reengage and close the needle eye 9 (FIG. 25A). The eye remains closed as the needle 411 moves in reverse direction to pull the bit B through the backing L to form a loop-tuft. During the return stroke (or loop-forming stroke) of needle 411, wedge 420 moves up to the correct position for the cam-surfaces 21L,21L to be engaged to open the needle eye for release of the loop-tuft (FIG. 25B) when the loop is a desired height corresponding with such position of the wedge. The positioning of wedge 420 may be effected by any suitable means (not shown) operated in timed relation to the needle bar. Before the empty needle 411 is again moved to pierce the backing L in the next tufting cycle, the wedge 420 is moved from engagement with cam-surfaces 21L,21L of the split-shank to position shown in FIG. 25A.

The split-tip needle 811 (FIGS. 25C,25D) is similar to split-tip needle 411 (FIGS. 25-25C), but simpler to manufacture because having no cam-surfaces 21U or 21L. In this modification, the elongated eye formed by the needle legs or shank elements 811A,811B is opened for threading, or for loop-tuft release, or both, by a rotatable cam 448 which reciprocates linearly with the needle bar. At desired times in the cycle of reciprocation of the needle, the cam 448 is moved angularly by suitable means not shown to spread the needle legs apart (FIG. 25C), thus to open the eye through the needle tip T, and is again moved angularly to permit the needle legs to come together, thus to close the eye and reform the needle tip (FIG. 25D). The eye control cam 448 may, as shown in FIGS. 25C,25D, be a flat-sided oval, but may be of any other suitable shape including those shown in FIG. 25E.

In FIG. 26, the reciprocating needle 411, or equivalent, repeatedly cooperates with wedge cam 420, or equivalent, to form successive tuft loops SL from a continuous strand S of tufting material mechanically fed to the needle from the supply spool SS or other source. The strand-feed mechanism 413 comprises the nip rolls 101,102 and the guide roll 100. While the needle is moving in direction to form a tuft-loop SL (from FIG. 25B to 25C) and while the backing L is being indexed to move the loop from the needle, the nip roll 102 is moved upwardly for cooperation with nip roll 101 in feeding of strand S to the needle-threading station shown and in part defined by plate 104. As shown, the plate 104 extends from guide roll 100 below the backing L and is apertured to clear the tip of the needle when in threading position with the eye below backing L. It is to be noted that the tufting needle is rethreaded by the strand in each cycle and that the loop tuft is freed from the needle in each cycle during or upon completion of the tufting stroke.

The plate 104 may extend across the entire width of the machine. The rolls 100,101 may be grooved, preferably less than the strand diameter, to maintain separation between the strands for adjacent tufting stations (FIG. 26B). The pairs of plates 108 guide the strands to their threading positions. The reciprocating movement of the feed roll 102 between its feed and non-feed positions may be effected by any suitable timed means including air-motors 103, cams (not shown) or the like.

Preferably and as shown in FIG. 26, the last-formed loop may be prevented from being shortened, or pulled out, while needle 411 is forming a loop by provision of a pair of clamping plates 105M,105S then pressing against the length of strand S which extends along the underside of backing L between these two loops. The clamping pressure is released during indexing of the backing L by its feed roll 15B and is subsequently reapplied in the next needle cycle. An array of interleaved clamping plates 105M,105S may extend across the entire width of the tufting machine (FIG. 26A) and a slight movement of the movable plates 105M between clamping and release positions effected by any suitably timed actuating means including cam 106, an air-motor, or the like.

If desired, and as shown for example in FIG. 26, the leading edge of a new length of backing L may be sewn to a lead strip LS with the temporary and removable stitching holding the

leading ends of the strands S, as extending forwardly from the loop SL of the first-formed row, against the underside of the backing.

With the arrangement shown in FIG. 26, the loop-tufts SL successively formed from a strand S fed to a particular tufting station may be of the same or different height depending upon the positioning of wedge 420 to open the needle eye after it has passed through the backing L in its loop-forming stroke. The positioning of wedge 420 of the tufting machine may be programmed to produce a sculptured effect of the tufted rug or other product.

However, with the arrangement shown in FIG. 26, all of the loops SL successively formed at a particular tufting station are of the same color or characteristics of the strand S fed from the associated source SS. By providing the tufting stations with individual multi-strand selectors such as shown, for example, in either of FIGS. 10 or 10A, any desired color pattern may be reproduced in the tufted product. The loop heights may be the same or different as discussed above. With any of such-multi-strand selectors, as used in combination with the basic arrangement of FIG. 26, each of the individual cutter bars associated with the multi-strand selector may have but a single knife and is programmed to sever a continuous strand only when the pattern demands a change in color, i.e., the selection of another strand.

For example, in FIG. 27, the multi-strand selector arrangement is the same as shown in FIG. 10A and described in connection therewith. The cutter bar disc 22 is attached to the driven element of a magnetic clutch 60 and is coupled to its drive shaft only when the clutch is energized under control of the color pattern. So long as there is no change in color required, the selected strand is intermittently fed, without cutting, in successive cycles of the machine for formation of tuft loops from a continuous length of that selected strand. The selected strand is mechanically fed by the nip rolls 101,102 directly into the threading station between plate 104 and the backing L.

Upon termination of a pattern demand for a particular strand color, the clutch 60 is energized to effect one revolution of the cutter disc 22 to sever the previously selected strand of that color. The clutch 53A of the strand selector is energized to select the new color strand as described in connection with FIG. 10A. The leading end of the newly selected strand in leaving the selector is pneumatically transported into the bite between cutter disc 22 and the anvil or disc 23 before termination of the revolution of cutter disc 22, at which time the rolls 22,23 are preferably slightly separated by suitable means synchronized with clutch 60. The leading end of the newly selected strand closely follows the trailing end of the old strand and is caught by the nip rolls 101,102 for feed into the threading station of split needle 411. Until there is another pattern demand for a new color, the last-selected strand is intermittently mechanically fed to the needle, without being cut into discrete bits, for formation of successive loops from a continuous length of that strand repeatedly threaded into the tufting needle means.

In both FIGS. 26 and 27, the needles are to substantial extent relieved of the load and wear incident, in conventional tufting machines, to feeding of yarn to the needles and formation of tufts therefrom: the yarn is also subjected to less tension in the yarn-feeding and tufting. In consequence, the production capability of the tufting machine over a substantial period of time is markedly enhanced because of lesser downtime for repairing yarn breakage and for needle replacement because of wear or breakage. In both FIGS. 26 and 27, the single split needle may be replaced by two split needles to form two loop tufts per cycle of reciprocation of the needle bar, in manner analogous to FIGS. 18,19, to increase the production rate.

It is, of course, to be understood that in FIGS. 26 and 27, the tufting needles used may be any of the split-tip types disclosed, or their equivalent, or may be split-side needles such as shown in FIGS. 19B,19C, or equivalent, all of which are suited

for rethreading in each needle cycle and for releasing a tuft-loop during, or upon completion of, a tufting stroke.

In all of the previously described tufting machines, the needles are moved up and down to pass through the backing in performance of a tufting operation while the backing is stationary in the interval between successive feeding movements of the backing, but it is to be understood the invention is also applicable to tufting machines of the type in which the needles are stationary and the backing is moved up and down to pass the needles through the backing in performance of a tufting operation in the interval between successive feeding movements of the backing.

In the modification schematically shown in FIG. 28, at each tufting station 120 the backing L and a strand S of tufting material pass between a rotary anvil means 123 and a rotary cutter means 122 which rotate in unison in opposite directions. During such rotation, the peripherally spaced blades of the cutter 122 in succession enter and leave peripherally spaced recesses 125 of anvil 123. Each blade 126 in turn slits the backing L and forces the strand S through the slit into an anvil recess 125 to form a loop tuft SL projecting from the wear side of the backing. The adjacent tufts SL are connected to one another along the underside of the backing by the base or intervening length C of strand between adjacent slits. The tufted backing is stripped from the rotary anvil/rotary cutter arrangement by suitable means such as stripper plate 129 and turn-roll 127 which presses against the tufted or pile side of the backing en route from the tufting station to a take-up roll (not shown) or other storage means.

The rotary anvil/rotary cutter means 122,123 may, and preferably do, serve as feed rolls which pull the backing L from a supply roll with the strand S from a supply spool SS in superposed relation suitably before they pass between these rolls.

The backing may be any of the conventional material, woven or non-woven, or a web or film because the sides of the slits into which the strands are forced by the blades hold the tufts in place as the blades retract.

If desired, the base portions C of the tufts may be bonded or locked to the underside of the backing L by any of various known techniques including those discussed in connection with FIG. 17. For example, hot polyethylene or other thermoplastic cement may be sprayed from the nozzles 128 against the underside of the backing. Setting of the cement may be accelerated by passing it over a cold pressure roll 85 which may also serve as a guide roll, or by subjecting it to blasts of cold air.

The basic rotary anvil/rotary cutter tufting arrangement shown in FIG. 28 dispenses with the tufting needles, the reciprocating needle-drive mechanism and the intermittent backing-feed mechanism used in the previously described modifications including that shown in FIG. 26. It will, of course, be understood by those skilled in the art that a row of tufting stations 120 (FIG. 28) extends widthwise of the backing L and each strand is forced by a set of blades 126 into anvil recess 125, thereby to form a series of loop-tufts projecting from one side of the backing with each loop-tuft connected to the next by an integral strand length C lying against the other side of the backing between adjacent slits lengthwise of the backing. The blades 126 for one tufting station may be in alignment with the blades 126 of the next tufting station (FIG. 30), axially of the common operating shaft 130 to provide a tufting pattern similar to FIG. 3A, or may be angularly offset or staggered to provide a different tufting pattern similar to FIG. 4A.

Any one or all of the tufting stations 120 may be preceded by a multi-strand selector arrangement such as shown, for example, in any of FIGS. 10, 10A and 27. Specifically and as shown in FIG. 29, the tufting station 120 is preceded by a multi-strand selector MS corresponding to that shown in FIGS. 10A and 27. For a detailed description of the construction and operation of the multi-strand selector MS, reference is made to the preceding description of FIG. 10A. It here suf-

fices to say that when the desired tufting pattern requires a change in the color, or other characteristics, of the tufting, the rotary cutter/rotary anvil means 22,23 makes one revolution to cut off the previously required strand and the gear 90 is indexed to that position for which the presently required strand is fed to the nip-rolls 101,102 for transport to the tufting station, all generally as described in connection with FIG. 27 except that the reciprocating tufting needle means of FIG. 27 is replaced by the rotary cutter/rotary anvil means 122,123.

In FIG. 29, the selected strand is guided from the nip-rolls 101,102 into the path of the blades 126 by a grooved guide plate or bar 133 (FIG. 29A) extending underneath and crosswise of the backing L and opposite to the bar or roll 134 which presses against the topside of the untufted backing L.

With the tufting arrangement as shown in FIGS. 28 and 29, all of the tufts formed by forcing the strands into the anvil recesses 125 are closed loops. All or some of the loops may be cut, as will now be described, to form a series of U-tufts, or a mixture of U-tufts and loop-tufts or other hybrid tufting pattern. In all cases when a loop-tuft is cut, the two free ends projecting from one face of the backing as pile elements are connected along the opposite face of the backing by an integral part C of strand S to tufting which has been forced through the adjacent slit of the backing.

As shown in FIGS. 30 and 31, one or more of the anvil recesses 125 may be provided with knife means 135 whose cutting edge is shaped to match the edge of the blade 126 of the rotary cutter means 122. Thus, as each blade 126 moves through its position of maximum insertion in an anvil recess 125 (FIG. 31), the tuft-loop is cut, so converting the tufting projecting through that slit from the pile side of the backing to two free-end pile elements, each connected by a strand portion C along the opposite side of the backing to tufting projecting from the adjacent slit. When, for example, any two adjacent anvil recesses 125 are provided with knife means 135, then two successive loop-tufts are cut to provide a U-tuft whose free ends respectively project from adjacent slits as tufting and whose base portion C lies along the underside of the backing to lock the U-tuft to the backing.

As shown in FIG. 32, the rotary cutter means 122 for a multiplicity of tufting stations may be an elongated roll providing for each station a set of peripherally spaced blades 126. The rotary anvil means for those stations may comprise a series of annular anvil discs 123, one per station, keyed to a common drive shaft and separated by annular washers 137 which jointly provide a segmented feed-roll surface. Each of the anvil discs 123 has peripherally spaced recesses 125 which receive the peripherally spaced set of blades 126, thus to serve as the tufting means for the corresponding station.

In dependence upon the desired overall tufting pattern, any one or more of the recesses of the same or different anvil discs 123 may be provided with knife means to cut the loop-tufts formed in recesses as above described.

For slitting the backing L and forcing a strand S into the anvil recess 125, the outer edge of each knife is suitably shaped to keep the strand between two spaced piercing tips T,T (FIGS. 33A-33D) which form the ends of a slit in the backing as the blade 126 begins its insertion in an anvil groove 125. The slit is completed as the blade forces the trapped strand through the backing into the recess. As shown in FIG. 33A, the piercing tips T,T may be the sharp ends of a wide, concave strand-retaining recess 138A in the outer edge of blade 126; as shown in FIG. 33B, the piercing tips T,T may be rather blunt rounded portions with an intermediate strand-retaining recess 138B; or, as shown in FIG. 33C, the piercing tips T,T may be upwardly and outwardly tapered edges with a narrow strand-retaining recess 138C. In FIG. 33D, the outer edge of blade 126 has piercing tips T,T similar to those shown in FIG. 33C, but the strand-retaining recess 138D is wider to accommodate two or more strands D to be simultaneously forced by the blade into an anvil recess. The various blade edges shown in FIGS. 33A-33D permit selection in dependence upon the characteristics of the backing to be used in

order to obtain optimum tufting performance of the machine and quality of the tufted product. In all of those configurations, the blade serves as a slitter-punch for the backing and a forked-end eyeless needle for the strand. To provide for cutting of tuft-loops, the strand-retaining recess of any of the blades 126 shown in FIGS. 33A-33D may be notched, as specifically shown in FIGS. 33A,33B, to provide an anvil for strand-severing knives 135 such as shown in FIG. 32; or, as shown in FIG. 33D, the blade 126 may have a knife 135A which is normally retracted by spring means 142B but which after formation of a tuft-loop is actuated as by cam 141B to cut the tuft-loop. In the latter case, the anvil recesses 125 serve as an anvil means both for blades 126 in slitting of the backing and for strand-severing knives 135A of blades 126 in cutting of tuft-loops.

When all blades 126 are of equal height, the loop-tufts SL formed in the anvil-recesses 125 during the tufting operation will all be of the same height. In FIG. 34, all of the blades 126 concurrently forming loop-tufts from different strands at different tufting stations are of the same height and accordingly the loop-tufts SL formed crosswise of the backing in the corresponding anvil recess are of the same height. Such equality of the height of tuft-loops successively formed at a single station, lengthwise of the backing, also obtains if the peripherally spaced knives for that station are all of equal height.

To produce tufts of different heights at the same and/or different tufting stations, blades 126 of different heights are employed. It is not necessary inversely to change the depth of the anvil recesses, but this may be done if desired. For example as shown in FIG. 35, some of the blades 126 are less than maximum height so that the loop-tufts SL concurrently formed at different tufting stations from different strands are of different height crosswise of the backing. Differences in the height of tuft-loops successively from a strand at any single station may be similarly obtained by using for that station peripherally spaced blades of different heights.

To produce closed-loop and/or cut-loop tufting with different heights of either or both forms of tufting, the anvil recesses 125 which are to produce cut-loop tufting are provided with knife means 135, and must be matched to the height of the associated blade 126. In FIG. 36, for example, two of the blades 126 are shorter to produce two low-loop tufts which are left uncut because of omission of knife means 135 from the associated anvil recesses: two of the anvil recesses 125 are provided with knife means 135 so to form cut loops SLC. In FIG. 36, the pattern of low, high, cut and uncut loops is crosswise of the tufting, and the loops are concurrently formed at different tufting stations from different strands. Clearly, however, any lengthwise pattern of low, high, cut and uncut loops successively formed at any tufting station may be obtained by using for that station peripherally spaced knives of different heights and by providing any one or more of the anvil recesses 125 with knife means 135.

In the tufting station arrangement shown in FIG. 37, the backing L and strand S pass between a rotary anvil 123 having peripherally spaced recesses and a rotary tufter 122 having peripherally spaced blades. In this modification, however, the blades move radially and they rotate into and out of the anvil recesses. This permits formation of longer tufts and/or closer spacing of successively formed tufts without danger of jamming or breakage of the blades. Specifically, each of the blades 126A (FIG. 37) is slidably mounted in drum 140 for radial movement controlled by cam means. Normally, the blades are retracted, but as each in turn comes into alignment with one of the anvil recesses 125, it is forced outwardly by the rise of cam 141 to slit the backing L and force the strand through the slit to form a tuft loop: as the blade further rotates with the drum, it is sharply retracted, under control of cam 141 by the spring means 142, so that its tufting end quickly clears the recess.

Preferably, the anvil 123 and the tufter 122 rotate step-by-step, and the tufting movement of each blade 126 is effected by one revolution of cam 141A (FIG. 38) while the anvil 123

and the tufter drum 140 are at rest in the interval between their successive indexing movements. The individual blades 126 of each peripherally spaced set may be provided with a cam-follower 143 for engaging a single cam 141A common to all tufting stations; or, as shown in FIG. 39, each of the peripherally spaced gang-blade bars 146 for all tufting stations may have two cam-followers 143, each for engaging a corresponding one of the two rotatably cams 141A respectively at opposite interior ends of drum 140 and driven via gearing including gear 130 to make 1 revolution for each indexing step of the rotary blade drum 122. A gang-blade arrangement with cam-followers at the opposite ends of each gang-blade may also be used with two cams of the groove type (not shown) instead of two face cams which require retraction springs for the blades.

In the modification shown in FIG. 40, the multi-station anvil 123A, instead of being an assembly of peripherally recessed discs and interposed washers, is an elongated roll with peripherally spaced grooves 125A extending from one end of the roll to the other. The associated multi-station tufting means 122 is of slotted drum construction similar to that shown in FIG. 39, but additionally includes spaced presser-foot rings 147. Each pair of rings 147 presses against the backing L on opposite sides of the strand being tufted and is of thickness to accommodate the strand. The rings 147 may be of metal (FIG. 41) and integral with the slotted drum 140; or they may be rings 147A of resilient material, such as "abrasion-resistant" rubber, tightly held in spaced grooves of the tufting drum 140 (FIG. 42), or such rings, as shown in FIGS. 43, 44, may each be a composite one comprising an inner resilient ring 147A and a steel outer ring 147B bonded thereto.

As shown in FIG. 39, the anvil means and the tufting means are indexed and are at rest when the knife means 126 slits the backing and forces the strand S through the slit. The presser-foot rings 147 are of assistance in that they hold the backing securely across the anvil recess (FIG. 44).

In the modification shown in FIGS. 45, 46, the rotary anvil may be of the slotted-cylinder type, such as shown in FIG. 40, or may be of the multi-disc type such as shown in FIGS. 34-36. The multi-station tufting means, though using a gang-blade 146 similar to that shown in FIG. 40, is not of rotary type, but is linearly reciprocable. With this tufting arrangement, the backing L is indexed by a drive-system separate and distinct from the tufting means. In the interval between successive feeding movements of the backing, the gang-blade is reciprocated to slit the backing and force the overlying strands through the slits into the associated recess or recesses of the anvil 123A. The different axial rows of anvil recesses may have different combinations of recesses with and without strand-cutting knives, so that in any interval between successive feeding movements of the backing and strands, the rotary anvil 123 may be indexed to the angular position corresponding with the desired row pattern of cut loop-tufts and/or uncut loop-tufts widthwise of the backing. Such indexing may be done manually or automatically by programmed control means (not shown) when a different row pattern is desired. Alternatively, the anvil 123A may be rotated step-by-step in synchronism with the multi-blade bar 146 to provide a repeating sequence of tufting-row patterns with uncut loop-tufts, cut loop-tufts, and/or both uncut and cut loop-tufts.

In the modification shown in FIGS. 47, 47A, the peripheral surface of the rotary anvil 123B comprises a series of flat-sided segments 150 in turn presented to a group of ganged tufting blades 146 when the anvil is indexed from one tufting position to the next. Each anvil segment 150 has a group of peripherally spaced rows of anvil recesses 125, the number of rows corresponding with the number of ganged blades 146 and the number of recesses 125 per row corresponding with the number of individual blades 126 per ganged blade 146. As shown in FIG. 47A, the ganged blades 146 are each slidably mounted in the stationary knife-support member 151 and each has a cam-follower roll 152 at its upper end exteriorly of

member 151. At each end of the individual blade gangs 146 and within the knife-support 151, there is provided a spring 153 whose upper end is engagable by a stop-shoulder 154 of the ganged blade 146. The lower end of spring 153 engages the bottom of the spring-cavity in member 151.

At the end of an indexing step, an untufted length of strand S lies, in the grooves of the group of blades 126, topside of the backing L, as shown in FIG. 47A. As cam 155 moves to the left, it, in turn, engages the cam-follower 152. In consequence, the blades 126 are in turn (from right to left) depressed to slit the backing L and, in turn, form loop-tufts in the corresponding anvil recesses 125A. With such sequential formation of the loop-tufts from strand S, each blade 126 of the group, during its tufting action, draws the length of strand necessary to form a loop without danger of breaking the strand by another blade of the group.

Before the next indexing of the anvil, the blade-cam 155 is returned to the position shown in FIG. 47A, and springs 153 retract the blade 126. Thus, when the next anvil segment is indexed to the position shown in FIG. 47, another untufted length of strand is pulled in a path defined by a notch in guide 133 and the edge-grooves of the blades 126. The blade-cam 155 may be actuated by any suitable means, preferably an air-cylinder motor.

The single cam 155 of FIG. 47A may be replaced, as shown in FIG. 47B, by a triple cam having cam-grooves 155A, 155B, 155C respectively receiving the cam-followers 152 for the blades 126. Again the blades 126 are, in turn, (from right to left) depressed to slit the backing and force the strand S into a corresponding anvil recess, thus sequentially to form a series of loop-tufts. In this modification, the blades 126 are withdrawn positively by the cam rather than by spring means, as in FIG. 47. Equivalently, the sequential tufting movement of the blades 126 may, as shown in FIG. 47C, be effected by a rotary arrangement using cams or eccentrics 155A, 155B, 155C which provide a positive drive for both the tufting and retraction strokes of the blades. Also, the ganged blades 146 may be actuated by individual air-motors, solenoids or the like (not shown) programmed to obtain the above-described sequential operation of blades 126.

The modification shown in FIG. 48 is similar to that shown in FIG. 47 in that for each indexing of the anvil two or more loop-tufts are, in succession, formed from each strand S at the corresponding tufting station. In FIG. 48, the blade-cam 155 for operating the tufting blades is omitted for clarity of illustration. The modification shown in FIG. 48 differs from that of FIG. 47 in that the rotary anvil 123B is replaced by a belt-anvil 123C whose anvil segments 150 are coupled by links 156. The belt-anvil 123C is looped over a pair of rolls 157, one of which serves as an idler roll and the other of which is provided with sprockets 158 to serve as the drive roll. The belt-anvil drive is indexed so that in each tufting cycle, one of the anvil-recess segments 150 stops with its rows of recesses in alignment with the ganged-blades 146 of the tufting head. While the belt-anvil 123C is at rest, the ganged-blades 146 are operated as described in connection with FIG. 47A, so that at each tufting station a group of blades 126 successively form two or more loop-tufts, each blade, in turn, slitting the backing and forcing another length of a strand S through the backing into the anvil recess below it. A bed-plate 159 below the top-flight of the belt-anvil 123C supports it to prevent appreciable flexing during the tufting operation.

Except in respects below discussed, the modification shown in FIG. 49 is similar to that shown in FIG. 48. In FIG. 49, the belt-anvil 123D is of tough rubber such as used in heavy-duty conveyors. The inner face of the belt-anvil is slotted or grooved to mesh with the teeth of rolls 157A, one of which is driven by the indexing mechanism, not shown. The anvil slots are formed by a series of spaced upstanding strips 160 of metal or other suitable material. The lower ends of strips 160 are embedded, as by molding, in the outer face of belt-anvil 123D and, for locking purposes, are of T or other suitable cross-sectional shape.

In the modification shown in FIG. 50, the belt-anvil 123E is similar to that shown in FIG. 49 except that the anvil recesses are formed by a series of spaced U-channels 161 suitably fastened to the outer face of the belt. The upper edges of the side strips of the U-channels are curled over to stiffen them and to increase the supporting area for the backing adjacent the regions where slotted by the tufting blades. In FIG. 50, the tufting is performed by rotary-blade means 122 generally similar to that shown in FIGS. 28-30 and other Figures. However, since the side-strips of the U-channels can tilt to some extent by virtue of their anchorage to a rubber belt, it is feasible to make reasonably long loop-tufts without breaking the blades 126.

Loop-tufts of still greater height or length may be obtained by replacing the rotary tufting member (FIG. 50) having fixed blades with a rotary tufting member having retractable blades, such as shown in FIGS. 37 to 44. Specifically in FIG. 51, the multi-tufting station arrangement comprises the belt-anvil conveyor 123E of FIG. 50 in combination with the retractable blade, rotary-tufting structure of FIGS. 40-44.

With the arrangement shown in FIG. 51, the belt-anvil 123D and the rotary-tufting structure are indexed in synchronism rather than moved continuously. With the next anvil recess in position to receive a tuft-loop, the cam 141A rotates to force the then retracted blade 126 of each station downwardly to slit the backing and force the strand through the slit into the recess. As shown in FIG. 52, during the formation of a loop-tuft, the side-strips of the recess-defining members 161 are forced away from one another. When the blade 126 is retracted, the side-strips spring back to their original position and the jaw means formed by their curled upper edges grip and hold the loop-tuft in the anvil recess.

In any of FIGS. 49, 50, 51, the belt-anvil there shown may be replaced by the belt-anvil 123F of FIG. 53. In this modification, the anvil-recesses are defined by columns or posts 162 integral with the rubber belt and preferably stiffened by the embedded metal pins 163. The corresponding columns 162 of each row, crosswise of the belt, are spaced from one another and connected near their tops by a small metal rod or wire 164, which may be rubber-coated. The columns of each row, lengthwise of the belt, are closely spaced in effect to form a continuous support for the overlying area of the backing as pressed down by the presser-foot rings 147 of the rotary-tufting blade member. As shown in FIG. 53, the loops are formed in anvil-recesses, each defined by two segments of adjacent wires 164 and four adjacent columns 162.

In any of FIGS. 47, 48, 49, the tufting-blade arrangement there shown may be replaced by that shown in FIG. 54, which also uses a group of blades which, for each indexed position of the anvil, sequentially forms a series of tuft-loops from each strand S. In FIG. 54, the blade support head 151A is reciprocable from and back to the position shown in the interval between successive indexing steps of the anvil. The shoulders 154 of the blades 126 engage the bottom of the spring recesses; and since the recesses are progressively deeper in the direction of feed of strand S, the edges of successive blades 126 are nearer and nearer to the topside of the backing L when the head 151A is in retracted position. As the head 151A descends, the blade 126 farthest to the right engages the backing and, when its spring 153 is sufficiently compressed, slits the backing and forces the strand into the anvil recess next to the loop last formed in the previous tufting cycle. As head 151A continues its descent, the next lower blade 126 engages the backing but does not slit it until its spring has been sufficiently compressed to slit the backing and force the strand therethrough. In the meantime, the strand S is free to slide below that blade if the first blade has not completed its tufting. In like manner, each of the remaining blades, in turn, slit the backing and form a loop-tuft from a length of strand which is free to move from the supply source.

When tall blades of the group have performed their operation, they are retracted and returned to the position shown in FIG. 54 by upward motion of their support head 151A.

To obtain different lengths for the loop-tufts formed at the same station or at different stations, each of the blades 126 may be provided with a threaded extension 166 which passes through a stop bar 165 above the support head 151A. The stop nut 167 for each blade 126 may be adjusted so that it engages stop 165 when the blade has formed a loop of desired depth in the anvil recess. If desired, the stop bar 165 may be moved upward from the position shown, when all blades have completed their tufting operation, to provide positive and simultaneous retraction of all blades. In such case, the stop bar 165 is returned to the position shown suitably before the next tufting operation of the blades.

It is to be understood that in any of FIGS. 47 et seq., any number of the anvil recesses may be provided with strand-severing means as discussed in connection with FIG. 30 and that the corresponding blades of the cutter may be complementarily notched as discussed in connection with FIGS. 33A, 33B to form a desired tufting pattern of cut loops or of cut and uncut loops. It will also be understood that the anvil and cutter combination of any of FIGS. 47 et seq. may be preceded by multi-strand selector means such as shown, for example, in FIGS. 9, 10, 10A, 14 and 27.

What is claimed is:

1. In a tufting machine for forming on a backing a pattern of U-tufts and loop-tufts, means for feeding said backing along a path of travel through said machine, a plurality of tufting means respectively for different stations of said machine, means supporting said tufting means for reciprocation from one side of said path of travel to the other side thereof, means for reciprocating said supporting means, the tufting means for one or more of said stations consisting of a pair of closed-eye needles disposed side-by-side with their eyes aligned, each pair of said closed-eye needles being adapted to form a U-tuft when threaded with a discrete length of tufting material on one side of the backing, the tufting means for one or more other stations comprising at least one split-eye needle having relatively movable eye-forming members, and means controlling relative movement of said eye-forming members of each of the split-eye needles as said tufting means is reciprocated to open their empty eyes for threading by a discrete or continuous length of tufting material on one side of the path of travel of said backing, to close the threaded eyes on said one side of said path of travel of said backing for passage through the backing, to open the eyes on the other side of the path of travel of said backing to release loop-tufts formed thereby, and to reclose the empty eyes for passage through the backing for rethreading.
2. In a tufting machine for forming on a backing a pattern of loop-tufts and U-tufts, means for feeding said backing along a path of travel through said machine, tufting means comprising at least one closed-eye needle and one split-eye needle disposed side-by-side with their eyes aligned for threading by a discrete length of tufting material when on one side of the backing to form said loop-tufts and U-tufts, means supporting said tufting means for reciprocation from one side of said path of travel to the other side thereof, means for reciprocating said supporting means, said split-eye needle having relatively movable eye-forming members, and means controlling relative movement of said eye-forming members of the split-eye needle when on the other side of the backing to release a loop-tuft formed thereby.
3. In a tufting machine for forming on a backing a pattern of loop-tufts and U-tufts, means for feeding said backing along a path of travel through said machine, tufting means consisting of two spaced closed-eye needles and at least one intervening split-eye needle,

means supporting said tufting means for reciprocation from one side of said path of travel to the other side thereof,
 means for reciprocating said supporting means,
 all of said needles having their eyes in alignment for threading by a discrete length of tufting material when on one side of the backing to form said loop tufts and said U-tufts, each of said split-eye needles having relatively movable eye-forming members, and
 means controlling relative movement of said eye-forming members of each of the split-eye needles as said tufting means is reciprocated when on the other side of said path of travel of the backing to release the loop-tuft formed thereby.

4. In a tufting machine for forming tufts on a backing,
 means for feeding said backing along a path of travel through said machine,
 a needle having spaced shank members normally forming an eye closed near the tip portion of the needle, the inner faces of said members having cam-engaging surfaces,
 means for supporting said needle for reciprocation from one side of said path of travel to the other side thereof,
 means for reciprocating said supporting means,
 cam means extending between said spaced shank members and coacting with said surfaces to spread said shank members apart to open said eye for threading with tufting material when on one side of said path of travel of said backing, and
 gas-flow means producing a differential of pressure to propel said tufting material to threading relation with said needle eye while opened by said cam means.

5. In a tufting machine for forming tufts on a backing,
 means for feeding said backing along a path of travel through said machine,
 a needle having spaced shank members normally forming an eye closed near the tip portion of the needle,
 means for supporting said needle for reciprocation from one side of said path of travel to the other side thereof,
 means for reciprocating said supporting means,
 cam means extending between said spaced shank members and rotatable to spread said shank members apart to open said eye for threading when on one side of said path of travel of said backing with tufting material, and
 gas-flow means producing a differential of pressure to propel said tufting material to threading relation with said needle eye while opened by said cam means.

6. In a tufting machine for forming tufts on a backing,
 means for feeding said backing along a path of travel through said machine,
 a needle comprising spaced shank members forming an elongated eye which is open for a first spaced relation of said shank members and is closed for a second spaced relation of said shank members,
 means for supporting said needle for reciprocation from one side of said path of travel to the other side thereof,
 driving means for reciprocating said supporting means,
 actuating means operating in timed relation with said driving means for effecting said first spaced relation of said shank members after the empty needle has passed to one side of said path of travel through the backing into a threading position for threading and again, after the threaded needle has returned through the backing to the other side of said path of travel, for release of tufting, and
 means for supplying tufting material through the open eye of the empty needle while in its said threading position to thread it for application to the backing as tufting.

7. In a tufting machine for forming loop-tufts on a backing,
 means for feeding said backing along a path of travel through said machine,
 a split-shank needle having shank members normally forming an eye closed near the tip portion of the needle,
 means for supporting said needle for reciprocation from one side of said path of travel to the other side thereof,
 means for reciprocating said supporting means.

means for controlling relative movement of said shank members toward one another to form an open hook-eye for threading when on one side of the backing and also relative movement of said shank members when on the opposite side of the backing to sweep a loop-tuft from said eye, and

means for transporting a discrete bit-length of tufting material or a bit-length of a continuous strand of tufting material to said one side of the backing for threading of said open hook-eye.

8. In a tufting machine for forming tufts on a backing,
 means for feeding said backing along a path of travel through said machine,

a needle having spaced shank members with free ends normally forming an eye closed near the tip portion of the needle, the inner face of at least one of said members having a cam-engaging surface,

means for supporting said needle for reciprocation from one side of said path of travel to the other side thereof,
 means for reciprocating said supporting means,

gas-flow means producing a differential of pressure to propel tufting material into threading relation with said needle while its eye is closed and is on one side of said path of travel, and

cam means extending between said spaced shank members and coacting with said surface to open said eye for release of a loop-tuft after the threaded eye has passed to the other side of said path of travel.

9. In a tufting machine for forming tufts on a backing,
 means for feeding said backing along a path of travel through said machine,

a plurality of tufting means respectively for different tufting stations,

means supporting said tufting means for reciprocation from one side of said path of travel to the other side thereof,
 means for reciprocating said supporting means,

rotary cutter and anvil means to cut discrete bits of tufting material from strands thereof,

said tufting means for at least some of said stations comprising a series of at least one split-eye needle and at least one closed-eye needle, all of which have their eyes in alignment, said split-eye needles having relatively movable eye-forming shank members,

means controlling movement of eye-forming members of each of the split-eye needles as said tufting means is reciprocated to open their empty eyes for threading by said discrete bits of tufting material on one side of the path of travel of the backing, to close the threaded eyes for passage through the backing on said one side of said path of travel of the backing, to open the eyes on the other side of the path of travel of the backing to release loop-tufts formed thereby, and

gas-flow means to propel bits from said rotary cutter and anvil means to each of said series of needles while their aligned eyes are on said first-named side of said path of travel of the backing.

10. In a tufting machine for forming tufts on a backing,
 tufting needle means,

a rotary cutter bar and anvil means for cutting bits from a strand of tufting material, said cutter bar having knives whose spacing predetermines the bit-length,

gas-flow means for transporting the successive bits, each to a position for threading of said tufting needle means, and means for effecting passage of said tufting needle means through the backing in timed relation to rotation of said cutter bar and providing a dwell, which without change of the timing relation, is sufficient for aforesaid transport and threading of bits of different lengths.

11. In a tufting machine for forming tufts on a backing,
 a row of threading stations crosswise of the backing on one side thereof,

tufting needles which pass through the backing into and from said threading stations,

- a plurality of strand-severing means, each comprising a rotatable cutter bar operating in timed relation to said tufting needles and having peripherally spaced knives to cut bits from a strand of tufting material, 5
 gas-flow means for transporting the bits from the respective cutter bars to threading position in a corresponding threading station, and
 means for effecting passage of said needles through the backing and providing a dwell thereof in said threading stations sufficient for the aforesaid gas-flow transport of 10 bits and threading of the needles.
12. In a tufting machine for forming tufts on a backing, means for feeding said backing along a path of travel through said machine, 15
 tufting means comprising at least one needle adapted to be passed through the backing to and from a threading position, means supporting said tufting means for reciprocation from one side of said path of travel to the other side thereof, 20 means for reciprocating said supporting means, rotary cutter/rotary anvil means, means for operating said rotary cutter, a multi-strand feed arrangement having gas-flow passages for respective strands of tufting materials, and 25 a plurality of solenoids, each having a plunger movable to engage and release the strand in a corresponding one of said passages, and selectively operable to permit feed of a selected strand to the threading position of said tufting means via said rotary cutter.
13. In a tufting machine for forming tufts on a backing, means for feeding said backing along a path of travel through said machine, 30
 tufting means comprising at least one needle passed through the backing to and from a threading position, means supporting said tufting means for reciprocation from one side of said path of travel to the other side thereof, means for reciprocating said supporting means, rotary cutter/rotary anvil means comprising a single rotary cutter, 35 means for operating said rotary cutter, a multi-strand feed arrangement having gas-flow passages for respective strands of tufting material, each of said passages at least in part formed by a deformable resilient tube, 40 a plurality of strand-restraining means, each comprising a pair of members normally squeezing between them one of said tubes to preclude feed of the strand therein, and a plurality of means, each selectively operable to control a pair of said squeezing members to allow the corresponding one of the tubes to assume a shape that permits feeding of the strand therein to the threading position of said tufting means via said single rotary cutter.
14. In a tufting machine for forming tufts on a backing, means for feeding said backing along a path of travel through said machine, 45
 tufting means comprising at least one needle passed through the backing to and from a threading position, means supporting said tufting means for reciprocation from one side of said path of travel to the other side thereof, means for reciprocating said supporting means, rotary cutter/rotary anvil means, 50 means for operating said rotary cutter, and a strand-feed arrangement comprising a gas-flow passage directed toward said rotary cutter/rotary anvil means, a rotatable spool having a passage for receiving a strand of tufting material from a strand-source, and programmed means for rotating said spool to a predetermined position for which the passage of the spool is in 55 alignment with said gas-flow passage for gas-flow feed of the strand to said rotary cutter/rotary anvil means.
15. In a tufting machine for forming tufts on a backing, means for feeding said backing along a path of travel through said machine,

- tufting means comprising at least one needle passed through the backing to and from a threading position, means supporting said tufting means for reciprocation from one side of said path of travel to the other side thereof, means for reciprocating said supporting means, rotary cutter/rotary anvil means, means for operating said rotary cutter, and a multi-strand feed arrangement comprising a plurality of gas-flow passages directed toward said rotary cutter/rotary anvil means, a plurality of rotatable spools, each having a passage for receiving a strand of tufting material from a strand-source, and programmed means for rotating said spools to any selected one of predetermined positions for which the passage of a selected one of said spools is in alignment with a corresponding gas-flow passage for gas-flow feed of the selected strand to said rotary cutter/rotary anvil means, the non-selected strands being restrained by having one or more turns on their respective spools.
16. In a tufting machine for forming tufts on a backing, means for feeding said backing along a path of travel through said machine, tufting means comprising at least one needle passed through the backing to and from a threading position, means supporting said tufting means for reciprocation from one side of said path of travel to the other side thereof, means for reciprocating said supporting means, rotary cutter/rotary anvil means for cutting bits from a strand of tufting material, means for operating said rotary cutter, gas-flow means for transporting the bits in turn to said tufting means when in threading position, and a multi-strand feed selector comprising a plurality of gas-flow passages directed toward said rotary cutter/rotary anvil means, a plurality of rotatable spools, each having a passage for receiving a strand of tufting material from a strand-source, and programmed means for rotating said spools to any selected one of predetermined positions for which the passage of a selected one of the spools is in alignment with a corresponding gas-flow passage for gas-flow feed of the selected strand to said rotary cutter/rotary anvil means, the non-selected strands being restrained by having one or more turns on their respective spools.
17. In a tufting machine for forming loop-tufts on a backing, means for feeding said backing along a path of travel through said machine, tufting means comprising at least one split-eye needle having a threading position on one side of the backing, means supporting said tufting means for reciprocation from one side of said path of travel to the other side thereof, means for reciprocating said supporting means, means to open the needle eye when in said threading position and again when in a loop-release position on the opposite side of the backing, means for feeding a strand of tufting material to said threading position of said tufting means, rotary cutter/rotary anvil means programmed to cut said strand upon termination of a pattern-demand for a strand of that color or other characteristic, and a multi-strand selector comprising a plurality of gas-flow passages directed toward said rotary cutter/rotary anvil means, a plurality of rotatable spools respectively having passages for receiving strands of tufting material of different color or other characteristic, and programmed means for rotating said spools to any selected one of predetermined positions for which the passage of a selected one of the spools is in alignment with a corresponding gas-flow passage for gas-flow feed of the selected strand to said rotary cutter/rotary anvil means.
18. In a tufting machine for applying tuft bits to a backing,

- means for feeding said backing along a path of travel through said machine,
- threading stations adjacent one side of the backing,
- tufting needles passed through the backing to and from the respective threading stations,
- means for supporting said needles for reciprocation from one side of said path of travel to the other side thereof,
- means for reciprocating said supporting means,
- strand-severing means for severing bits from strands of tufting material,
- gas-flow means including flow passages extending to said threading stations respectively for propelling the severed bits from said strand-severing means to said needles with each bit in threaded relation with at least one of said needles for application of said bits to the backing,
- bit-stop means for each threading station comprising a deformable resilient tube serving as an extension of the corresponding flow passage, and
- means for squeezing each tube to form a constriction arresting a bit in position for its application to the backing.
19. In a tufting machine for applying tuft bits to a backing,
- means for feeding said backing along a path of travel through said machine,
- threading stations adjacent one side of the backing,
- tufting needles passed through the backing to and from the respective threading stations,
- means for supporting said needles for reciprocation from one side of said path of travel to the other side thereof,
- means for reciprocating said supporting means,
- strand-severing means for severing bits from strands of tufting material,
- gas-flow means including flow passages extending to said threading stations respectively for propelling the severed bits from said strand-severing means to said needles with each bit in threaded relation with at least one of said needles for application of said bits to the backing,
- bit-stop means for each threading station comprising a deformable resilient tube serving as an extension of the corresponding flow passage, and
- adjustable means for squeezing each tube at a variable distance to form a constriction arresting a bit in desired position for its application to the backing.
20. An assembly of tufting needles comprising
- a pair of mounting members, at least one of which is relatively movable with respect to the other,
- each of said tufting needles having shanks respectively anchored into said mounting members and projecting therefrom in side-by-side spaced relation,
- one shank of each needle having a relatively sharp tip portion and a shoulder portion forming part of the eye of the needle and the other of said shank members having a shape complementary to said shoulder portion so that when said shank members are in juxtaposition there is formed the eye of the needle for carrying tufting yarn,
- means for feeding backing along a path of travel adjacent said assembly of tufting needles,
- means supporting said mounting members for reciprocation of said tufting needles from one side of said path of travel to the other side thereof,
- means for reciprocating said supporting means, and
- means for operating said mounting members simultaneously to open and close the eyes of said needles.
21. The assembly of claim 157 in which means are provided for concurrently opening the eyes of all needles when on one side of said path of travel of the backing to receive tufting yarn and for concurrently closing said eyes while on said same side of said path of travel of said backing for movement of the tufting yarn through the backing to form a plurality of tufts.
22. In a tufting machine for forming tufts on a backing,
- means for feeding said backing along a path of travel through said machine,
- tufting means comprising at least two split-shank needles disposed side-by-side with aligned eyes, each of said split-shank needles having two spaced shank members forming

- an elongated eye which near the tip portion of the needle may be opened or closed by relative movement of said shank members,
- means supporting said tufting means for reciprocation from one side of said path of travel to the other side thereof,
- means for reciprocating said supporting means, and
- cam means disposed between said shanks for effecting relative movement of them to open said eyes when on one side of said path of travel of the backing for threading of them by lengths of tufting material and to close said eyes when on the opposite side of the path of travel of the backing for release of loop-tufts formed from said lengths of tufting material.
23. The tufting machine of claim 159 in which said shanks in the position for closing said eyes present substantially parallel opposing surfaces,
- rotatable cam means for opening said eyes, and
- means for operating said cam means to open said eyes at any selected longitudinal position of the shanks relative to said cam means.
24. The tufting machine of claim 159 in which the opposing surfaces of said shank portion are movable relative to said cam means without opening said eyes, the opening of said eyes being due solely to rotation of said cam means.
25. In a tufting machine for forming tufts on a backing,
- means for feeding said backing along a path of travel through said machine,
- a pair of mounting members,
- tufting means comprising at least two split-eye needles disposed side-by-side with aligned eyes, each of said split-eye needles having two spaced shank members which are respectively attached to said mounting members and which form an elongated eye extending toward the tip portion of the needle,
- means for supporting said mounting members for reciprocation from one side of the path of travel of a backing to the other side thereof,
- means for reciprocating said supporting means, and
- means for moving one or the other or both of said mounting members to open the eyes of said split-eye needles when on one side of said path of travel of the backing for threading thereof with a length of tufting material and to close said eyes when on the opposite side of said path of travel of the backing for release of loop-tufts formed from said length of tufting material.
26. In a tufting machine for forming tufts on a backing,
- means for feeding said backing along a path of travel through said machine,
- a pair of mounting members,
- tufting means comprising at least two split-eye needles disposed side-by-side with aligned eyes, each of said split-eye needles having two spaced shank members which are respectively attached to said mounting members and which form an elongated eye extending toward the tip portion of the needle,
- means for supporting said mounting members for reciprocation from one side of the path of travel of a backing to the other side thereof,
- means for reciprocating said supporting means, and
- means for moving one or the other or both of said mounting members to open the eyes of said split-eye needles when on one side of said path of travel of the backing for threading with a length of tufting material, to close the threaded eyes on said one side of said path of travel of said backing for passage through the backing, to reopen the eyes when on the other side of said path of travel of the backing for release of loop-tufts formed from said length of tufting material, and to reclose the empty eyes for passage through the backing for rethreading.
27. In a tufting machine for forming loop-tufts on a backing,
- means for feeding said backing along a path of travel through said machine,

a split-shank needle having shank members with free ends normally forming an eye closed near the tip portion of the needle,
 means supporting said needle for reciprocation from one side of said path of travel to the other side thereof,
 means for reciprocating said supporting means,
 cam means intermediate of and engaging at least one of said

shank members to open said eye when on one side of said path of travel of the backing for threading and for again opening said eye when on the other side of said path of travel of the backing for release of a loop-tuft, and
 5 means for threading the needle eye when open on said first-named side of said path of travel of the backing.

UNITED STATES PATENT OFFICE
CERTIFICATE OF CORRECTION

Patent No. 3,670,672

Dated June 20, 1972

Inventor(s) Abram N. Spanel

It is certified that error appears in the above-identified patent
and that said Letters Patent are hereby corrected as shown below:

Column 21, line 73, change "he" to "the".

Column 23, line 8, change "rotatably" to "rotatable".

Column 25, line 73, change "tall" to "all".

Column 31, line 64, change "157" to "20".

Column 32, line 14, change "159" to "22",

line 22, change "159" to "22".

Signed and sealed this 6th day of March 1973.
